COIL WINDING MACHINE

James S. Burge, Anderson, Ind., assignor to General Motors Corporation, Detroit, Mich., a corporation of Delaware

Application July 26, 1940, Serial No. 347,701

90 Claims. (Cl. 242—10)

This invention relates to coil winding machines and more particularly to machines for winding a plurality of coils simultaneously upon an arbor. A type of coil for which the present machine is particularly adapted is the secondary winding of an ignition coil. Such a coil comprises several thousand turns of fine wire wound in layers separated by wrappings of insulating paper.

It is an object of the present invention to provide a coil winding machine which is automatic in operation wherein the winding of each layer of wire of each coil is followed by the winding upon the arbor of a strip of paper wide enough to span all of the coils and wherein the winding of the succeeding layer of each coil automatically follows the winding of the paper strip. At certain intervals during the winding of wire and paper upon the arbor, the paper layers are automatically severed at places between the ends of the layers of wire. When the machine is once placed in the status of automatic operation, it will stop automatically after a predetermined number of layers of wire and paper have been wound thereon. The machine will stop automatically at any time in response to the breaking of any of the wires leading from the supply reels to the winding arbor.

In the disclosed embodiment of the present invention these objects are obtained by the provision of a primary drive of a relatively high speed through which the winding arbor and the wire guide feed screws are driven. In addition to the primary drive, a secondary drive of low speed is connected to the power source for operating the mechanisms for feeding the strip of paper from a supply reel to the arbor for causing the arbor to rotate to wind a predetermined number of turns of paper thereon and for causing the paper on the arbor to be severed from the supply strip. This secondary drive also furnishes power to the means for automatically severing the paper layers circumferentially between the coil windings. At the end of the winding of a layer of wire a predetermined number of turns, the arbor is automatically disconnected from the primary drive. The secondary drive is then automatically connected with the mechanism for feeding paper to the winding arbor. The winding arbor is automatically connected with the secondary drive in order that it may rotate to wind a predetermined number of turns of paper thereon and then the paper is automatically sheared from the supply. After this has been accomplished the secondary drive

is automatically disconnected from the paper feed mechanism and paper shearing mechanism and from the arbor; and the arbor is automatically reconnected with the primary drive in order to continue winding the wire thereon at high speed.

The wire is guided to the arbor for winding in even layers by means of guide wheels rotatably supported by a traverse bar which moves parallel with the arbor through the operation of feed screws and nuts connected with the bar. Certain motions of the traverse bar automatically effect the connection between the secondary drive and the mechanism for severing the layers of paper between the coil winding. Following operation thereof, the severing mechanism is automatically disconnected from the secondary drive.

When a predetermined number of layers of wire and paper have been wound upon the arbor the primary drive is automatically disconnected from the source of power and the machine stops.

The present machine includes other important features which will become apparent from the following description reference being made to the accompanying drawings.

Fig. 1 is a perspective view from the front and right side of the machine.

Figs. 2 and 3 taken together constitute a front view of certain parts of the machine.

Fig. 4 is a fragmentary front view of an element shown in smaller scale in Fig. 3 and forming a part of the mechanism for automatically effecting the connection of the secondary drive with the paper layer severing mechanism.

Fig. 5 is a sectional view on line 5—5 of Fig. 4.

Fig. 6 is a fragmentary longitudinal sectional view showing a portion of the winding arbor with a coil tube thereon and a portion of the arbor tail stock.

Fig. 7 is a plan view of the mechanisms at the right end of the machine, a portion of the inclosing casing being shown in section.

Fig. 8 is a perspective view of the mechanism shown in Fig. 7. This view being taken from a position slightly in front of and well above the machine.

Fig. 9 is a fragmentary sectional perspective view of the machine shown in Fig. 7, taken in the direction of the arrow 9 of Fig. 7.

Fig. 61 is a right end view of the controls of the machine looking in the direction of the arrow 61 of Fig. 57.

Fig. 62 is a fragmentary view showing a support for a wire reel said support carrying an unreeeling arm and a pedestal supporting a switch which is automatically closed when the wire breaks.

Fig. 63 is a view in the direction of arrow 62 in Fig. 62.

Fig. 64 is a sectional view on the line 64-64 of Fig. 63 and is drawn to a larger scale than Fig. 62.

Fig. 65 is a fragmentary sectional view on line 65-65 of Fig. 64 and is drawn to a larger scale than Fig. 64.

Fig. 66 is a fragmentary sectional view on line 66-66 of Fig. 65.

Fig. 67 is a fragmentary sectional view on line 67-67 of Fig. 66.

Fig. 68 is a diagram of the principal operating mechanisms of the machine and controls therefor.

Reference will first be made to Fig. 68 on sheet 28 showing diagrammatically the principal mechanisms of the machine. A drive pulley A connected with the power source drives a shaft B at relatively high speed. Shaft B may be connected by clutch C with a pulley D connected by belt E with a pulley F driving a shaft G which drives the arbor H. Shaft G is connected by suitable gearing with feed screws I and J cooperating with a nut K connected through a screw coupling L with a rod M which moves parallel with the arbor H and carries a plurality of wire guide wheels N. It will be understood that the nut K engages alternately with the screws I and J so that the guide wheels N will be caused to move in opposite directions parallel with the arbor to guide the wire thereon in even layers. Shaft H is connected through a geared shaft O with a turn counter P. The transmission from the drive pulley A to the arbor H including the elements B, C, D, E, F and G provide the primary drive for the arbor. It is through this primary drive that the arbor is driven at high speed for winding wire thereon. Incidental to the winding of paper thereon, the arbor is driven at slow speed through a secondary drive which will now be described.

The secondary drive of the machine is provided by speed reducing gearing in gear box Q connecting shaft B with shaft R. Shaft R drives a gear S meshing with a gear T which, through a one-revolution clutch U is connected with a sprocket V when the clutch is operative. Sprocket V is connected by chain W with a sprocket wheel X which is connected by a manually controlled clutch Y with a cam shaft Z carrying a hand-wheel AA by which shaft Z may be manually operated. Shaft Z is connected by bevelled gears BB with a layer counter CC. Shaft Z drives brake cam DD which, through a control represented by arrow DD-1, controls a brake EE for frictionally resisting rotation of a shaft FF upon which the paper supply roll is mounted. Shaft Z drives shear cams GG which operate the mechanism for shearing paper wound upon the arbor from the paper supply. Shaft Z drives a gear HH meshing with a gear II which, through a clutch JJ, may be connected with a shaft KK which drives a paper feed roll by which paper is pulled from the supply roll and is delivered to the winding arbor preparatory to being wound thereon. Gear HH meshes with gear LL which, through a clutch MM is connected with the shaft G which drives the arbor H. Shaft Z drives gear NN meshing with gear OO which drives at half the speed of shaft Z a cam PP. Arrow PP1 indicates a mechanism connected with cam PP for shifting the nut K from one feed screw to the other. Arrow PP2 indicates a mechanism operated by cam PP for rotating the screw coupling so that the wire guide rod M will be shifted slightly longitudinally at the time the feed nut K is shifted. This is desirable in order that the end turns of layers of wire will not be directly superposed one upon the other, but will be in a slightly staggered relation. The secondary drive for the arbor therefore comprises all of the mechanism which is driven by the low speed shaft R.

The clutch U connects shaft R with the arbor H at a time when arbor H is disconnected from shaft B by opening clutch C. The disconnection of clutch C and the connection of clutch U is effected automatically in the following manner: The turn counter P operates through a mechanism represented by arrow QQ to open the clutch C at the end of winding of a layer of wire. Con-

currently with the opening of clutch C, the turn counter P operates through a mechanism represented by arrow RR to cause a one-revolution clutch SS to connect a low speed shaft TT with a main control cam UU. Cam UU operates through a mechanism represented by arrow VV to close the clutch U connecting gear T with pulley V. It will be understood that clutches U and SS open automatically at the end of one revolution. During the time that clutch SS is closed clutch U is also closed. During the time the clutch U is closed shaft Z turns one revolution provided clutch Y has been manually closed. One revolution of shaft Z causes arbor H and a paper feed shaft KK to be rotated to cause paper to be withdrawn from the supply roll and about three turns thereof to be wound upon the arbor together with an equal number of turns of wire. Clutches JJ and MM are normally disengaged, but when gear HH begins to turn, these clutches almost immediately engage so that the paper feed shaft KK will be rotated for the purpose of presenting the leading edge of the paper strip to the arbor and wires leading thereto and for the purpose of rotating the arbor H to wind about three turns of paper thereon. After the arbor begins to wind the paper thereon the clutches JJ and MM are automatically opened. At the end of one revolution of cam shaft Z the clutch is automatically opened. During one revolution of cam shaft Z, feed nut shifter cam PP moves one-half revolution to cause nut K to be shifted from one feed screw (I or J) to the other. By the time that one revolution of main control cam UU has been completed, the main clutch C will have been reconnected through a mechanism operated by cam UU and represented by arrow UU2.

It is therefore apparent that the present invention provides means responsive to completion of a layer of winding for disconnecting the arbor from the primary drive (through elements B, D, E, F and G) and for initiating a cycle of operation which results in connecting the arbor with the secondary drive (elements R, S, T, U, V, W, X, Y, Z, HH and MM). This cycle is initiated by the automatic closing of clutch SS in response to the completion of a layer of winding. Clutch SS causes main control cam UU to rotate; and main control cam UU causes clutch U to be closed so that shaft Z will be connected with the power source through the secondary drive. Disconnection of arbor H from the secondary drive is effected automatically by the completion of one revolution by shaft Z. Shaft Z stops automatically because clutch U opens automatically at the end of one revolution. The arbor H is reconnected with the primary drive automatically through main control cam UU by the time it has completed one revolution. Cam UU then stops because clutch SS automatically disconnects cam UU from shaft TT. Then another layer of wire is wound upon the arbor and the wire guide wheels traverse the arbor in the opposite direction until that layer is completed and the cycle of control is repeated, the arbor being again disconnected from the primary drive and then reconnected with the secondary drive so that another wrapping of paper may be applied to the wire then on the arbor. The operation of high speed winding of a layer of wire alternating with the low speed operation of winding a paper wrapping over the layer of wire will continue until the number of layers reach a predetermined number. When this condition obtains, the layer counter CC closes a switch a

which connects a current source with a solenoid winding *b*, thereby attracting downwardly a solenoid armature *c* thereby causing toggle links *d* and *e* to be moved into the position shown. This causes a starting lever *f* pivoted at *g* to move into non-operating position by the action of a spring *h* through a mechanism, represented by the arrow *i* in dot-dash lines, to cause the main clutch *C* to open. Each strand of wire leading from a supply reel to the arbor controls a switch *928*. Whenever a wire strand breaks, switch *928* closes to connect the current source with solenoid coil *d* which operates to cause the opening of main clutch *C*. Signal lamp *s* burns to indicate operation of solenoid *b*.

The paper wrappings are intermittently severed at points between coil windings by a plurality of razor blades *RB* mounted on a rocker shaft *RS*. Rocker shaft *RS* is operated by blade operating mechanism *BO* which operates in conjunction with a blade distance control mechanism *BD* which determines automatically the angular distance through which the rocker shaft *RS* moves each time it is operated by the blade operating mechanism *BO*. Arrows *BO1* and *BD1* represent the mechanical connection between elements *BO*, *BD* and *RS*. It will be understood that when the diameter of the windings is small, the rocker shaft *RS* must move a greater distance than when the diameter of the windings is large. This is necessary since it is desired that the razor blades *RB* move only far enough to sever the layers of paper which have not previously been separated.

The blade operating mechanism *BO* is connected to a one-revolution clutch *WW* with a shaft *VV* constantly driven by shaft *R* through sprocket *VV1*, chain *VV2* and sprocket *VV3*. The clutch *WW* is closed automatically by mechanism represented by arrow *WW1*, which is moved in response to movement of wire guide wheel rod *M* in one direction. It has not been found necessary to operate blades *RB* each time a wrapping of paper is applied to the arbor. Blades are caused to cut the paper following each two wrappings of paper upon the arbor.

After the winding of a set of coils upon the arbor has been completed, the status of the blade distance control mechanism *BD* will be such that the blades *RB* will be moved the minimum distance from the rest. In order to recondition the mechanism *BO* so that the razor blades will be moved the maximum distance required for cutting coil wrappings of minimum diameter, the operator manipulates a reset lever *j* which through a connection represented by arrow *j1* causes the device *BD* to be reset or restored to the condition required when beginning to wind a new set of coils on the arbor. The lever *j* also controls the brake *EE* through a connection represented by *j2* for a purpose to be described later.

Other controls of the machine include a lever *k* which operates a latch mechanism *k1*, to allow shifting of the clutch *Y* into engagement, by a spring which pulls up on a pedal *l*. The closing of clutch *Y* will complete the secondary drive to the arbor *H* so that it will be turned automatically when clutch *U* is closed. Clutch *Y* is opened by depressing pedal *l*, which is held down by the latch mechanism *k1*, until released again by lever *k*. Pedal *l*, operating through mechanism *l2*, when pressed down prevents the closing of clutch *WW*. Thus the depressing of lever *l* prevents the possibility of automatic winding

of paper upon the arbor and the advancing of the blades *RB* toward arbor. This status is desirable while the operator is manipulating the machine preparatory to the automatic functioning thereof.

A pedal *m* through a mechanism *m1*, operates the knife rocker shaft *RS* in order to sever the paper wrappings independently operative of automatic mechanism *BO*.

A pedal *n* is provided for the purpose of operating a mechanism (not indicated on the diagram) for shifting a supply roll of paper from a storage position into an operating position represented by the line *FF* in the diagram. Having described the principle of operation of the machine with reference to Fig. 68, I will now proceed to describe the construction of the machine in detail.

Primary drive to the winding arbor

Referring to Figs. 32, 33 and 34, 38 to 43, the drive pulley *A* is driven by a belt *100* passing over a pulley *101* driven by electric motor *102* (Fig. 57). Shaft *B* driven by pulley *A* is journaled in bearing *103* mounted in frame *104* attached to plate *105* which is mounted upon table *106*. Shaft *B* is journaled in bearing *107* mounted in gear box *Q* and in bearing *108* mounted in block *109* attached to gear box *Q* which is mounted upon plate *105*. Shaft *B* passes through a sleeve *110* supported by sleeve *111* mounted upon the bearing frame *104*. Sleeve *111* supports the inner races of ball bearings *112* the outer races of which are mounted within pulley *D*. The right face *114* of pulley *D* is flat and provides a clutch surface for engaging a clutch friction disc *115* fastened to a metal plate *116* having a hub *117* slidable along the shaft *B* and connected therewith by the splines *118*. The leather disc *115* and the face *114* constitute the clutch *C* of the diagram Fig. 68. Clutch *C* is engaged when disc *115* is pressed against disc *114* by a mechanism to be described later.

Belt *E* connects pulley *D* with pulley *F* on shaft *G*. (Fig. 44.) Shaft *G* (Fig. 44) is journaled in bearings *120* and *121* mounted respectively in walls *122* and *123* of frame *124* mounted on plate *125* (Fig. 33) which is mounted on table *106*. Shaft *G* is connected with an aligned shaft extension *G1* journaled in bearings *126* and *127* mounted in a bearing sleeve *128* attached to wall *122* and journaled in a bearing *129* mounted in a pedestal *130* which is attached to the plate *125*. The shaft extension *G1* provides an arbor head stock member *131* having a socket *132* (Fig. 44) for receiving the left end of the arbor *H* which is provided with a cross slot *133* for receiving the pin *134* driven by shaft *G1*. The right end of the arbor *H* (see Fig. 6, sheet 3) is supported by a sleeve *135* journaled in a bearing *136* supported by a sleeve *137* supported for horizontal sliding movement on pedestal *138* mounted on plate *125*. The sleeve *137* provides the tail stock for the arbor *H* and is moved into arbor supporting position by a handle *140* extending through a slot *141* and attached to the sleeve *137*. By moving the handle along the slot *141* toward the left, the tail stock sleeve *137* will be moved into proper position for supporting the arbor *H*. The sleeve *137* is retained in this position by moving the handle *140* downwardly into a notch *142* extending downwardly from the left end of slot *141*. The handle *140* is retained in this position by a lever *143* having a notch *144* for receiving the handle *140*. Lever *143* is pivoted at *144*

on a bracket 145 supporting a spring 146 which urges the lever 143 counterclockwise so that it will yieldingly engage the handle 140.

The primary drive for the arbor comprising pulley D connected by clutch C with shaft B, belt E, pulley F and shaft sections G and G1 operate the means for guiding the wire to the arbor so that a smooth flat winding layer will be formed. Shaft G (Fig. 44) is splinedly connected with a sleeve 150 fastened to a gear 151 meshing with a gear 152 and fastened to a gear 153 meshing with a gear 154. Gears 152 and 154 are fixed to a sleeve 155 providing also a gear 156 meshed with a gear 157. Sleeve 155 is connected with shaft 158 providing screw I; and gear 157 is connected with shaft 159 providing screw J. Shafts 158 and 159 are journaled in bearings provided by frame walls 122 and 123. Sleeve 150 is slidably supported by a bearing 160 mounted in plate 161 fastened to frame 124 and providing a cover for housing 162 which encloses the gears heretofore mentioned. In the position of sleeve 150 shown in Fig. 44, gear 151 is out of mesh with gear 152 while gear 153 is in mesh with gear 154. It is therefore apparent that the feed screws I and J will be rotated at a relatively high speed to provide relatively coarse spacing of the wire turns. Sleeve 150 supports a hand wheel 163 by which the arbor H and the feed screws I and J may be manually rotated. Hand wheel 163 is used to move the sleeve 150 along shaft G so as to demesh gear 153 from gear 154 and mesh gear 151 with gear 152. In this latter status of the gearing, the feed screws I and J will be rotated relatively slowly so that the turns of wire wound upon the arbor will be closely spaced.

The screws I and J cooperate with half nut members 168 and 169, respectively, mounted upon a lever 170 loosely journaled on a rod 171 and, as shown in Fig. 2, that confines between a collar 172 pinned to the rod and a lever 173 pinned to the rod. Rod 171 extends through a tube 174 and that part of the rod within tube 174 is screw threaded as indicated by 175 in Fig. 32. Rod 171 and the tube 174 are supported for horizontal sliding movement by walls 123 and 122 of frame 124. While nut member 168 engages rotating screw I the rod 171 will be moved horizontally in one direction and, in the opposite direction, while nut 169 engages rotating screw J. In order to prevent any accidental horizontal movement of rod 171 (Fig. 39) during the shifting of lever 170 in order to change the direction of feed, the screw threaded portion 175 of rod 171, which is exposed by cutting away a portion of the sleeve 174 to provide the flat surfaces 180 and 181 (Fig. 43a), is engaged by a nut 182 during the time neither of the nut sections 168 or 169 engage a screw I or J. The nut 182 (Fig. 43a) is carried by a lever 183 pivoted on stud 184 fastened to wall 122. Lever 183 is urged counterclockwise by a spring 184 fixed to the lever 185 attached to wall 122. Whenever lever 170 is rotated upon the rod 171 for the purpose of disengaging a nut section 168 or 169 from one of the feed screws and engaging the other nut section with the other feed screw, the rod 171 is caused to rotate in order that the nut 182 will be disengaged from the screw 175. By the time that one of the nut sections 168 or 169 has been engaged with a feed screw, the disengagement of the nut 182 from screw 175 is effected by engagement of one or the other of the flats 180, 181 with the lever 183.

The mechanism for rotating the levers 170 and

173 will now be described. In Fig. 33 the cam PP operated by the secondary drive provides a race 190 receiving a roller 191 carried by a lever 192 which is pivoted at 193. Lever 192 carries an ear 194 through which a rod 195 extends. Rod 195 is coupled at 196 to a rod extension 197 having a universal joint connection 198 with lever 170. The rod 195 screw threadedly receives pairs of nuts 199 and 200, and loosely supports sleeves 201 and 202. A spring 203 is located between nuts 199 and sleeve 201. A spring 204 is located between nuts 200 and sleeve 202. The pairs of nuts 199 and 200 are adjusted so as to place springs 203 and 204 under compression so as to urge the sleeves 201 and 202 against the ear 194 of the lever 192. As shown in Fig. 33 the roller 191 is located in the outer part of cam race 190, and lever 192 leans toward the left. In this position of lever 192, spring 203 yieldingly urges the rods 195 and 197 toward the left and the lever 170 counterclockwise and the nut section 169 is caused to yieldingly engage the screw J. As will be explained later, each cycle of movement of the secondary drive causes the cam PP to rotate 180°. Therefore, at the end of the next cycle of movement of the secondary drive, the roller 191 will be located in that part of the cam race 190 which is near to the center of the cam, thereby causing the lever 192 to lean toward the right in Fig. 33. In that position of the lever 192, the spring 204 will exert yielding pressure through the rods 195, 197 and lever 170 to cause the nut section 168 yieldingly to press against the screw I.

Whenever the lever 170 is moved the lever 173 is moved also. For this purpose the lever 192 carries a block 206 which pivotally supports a coupling 207 attached by pin 208 to a clevis 209 fastened to rod 210 having a swivel coupling at 211 with the lever 173. The mechanism for shifting the lever 170 can be so proportioned that relative to the mechanism for shifting lever 173 that end of the nut sections 168 or 169 can be caused first to engage a screw I or J before final movement of the lever 192 is completed. The overtravel of the lever 192 is taken up by compressing one or the other of the springs 203 or 204. In this way the one or other of the screws I or J will be engaged by a nut section 168 or 169 before final movement of lever 173 takes place to lift the nut 183 out of engagement with screw 175 through the coaction of the sleeve 174 which is pinned to the shaft 171.

A member 212 having a helical groove is keyed to rod 171 and its helical groove receives a ball 213 retained by a hub 214 within which the member 212 extends. The hub 214 is prevented from moving endwise along the member 212 and since it is provided with an internal annular flange 215 confined between member 212 and nuts 216 threaded on the end of rod 171. The hub 214 is integral with an arm 220 which (Fig. 43) is connected by a pin 221 with a collar 222 clamped by the turning of a screw 223 to wire guide wheel rod M. The parts 212, 213 and 214 provide the screw coupling L of Fig. 68.

The ends of rod M (Figs. 2 and 3) are supported by clamp collars 225 and 226. Collar 225 is supported by a pair of rollers 227 which are received by a groove 229 in a track plate (Fig. 43). Clamp collar 226 is supported by a single roller 228 received by a groove 230 in a track plate 232 (Fig. 24) which is supported by tail stock pedestal 138. Thus the rod M is supported and guided for horizontal movement parallel to the arbor H.

As shown in Fig. 1 the machine is equipped to wind 10 coils 921. The wire for these coils is unreeled from supply reels 913 which is guided by arms 914 and directed over pulleys 918 supported by pedestals 920. The wires, one of which is indicated at 917 in Fig. 11, are each passed around a wire guide wheel N. Each wheel N is journaled on a ball bearing 235 (Fig. 12), the inner race of which rests on bushings 236 located between the forks 237 of a bifurcated bracket 238. Bushings 236 are supported by a screw 239 extending through the arms 237 and receiving a nut 240. The clamp brackets 238 are supported by the rod M and are secured thereto in the desired spaced relation by a tightening of screws 241 (Fig. 11).

The rotation of lever 173 not only controls the engagement of the nut 182 with the screw 175 (Fig. 43a) but also operates through the screw 212 and ball 13 to effect a slight longitudinal movement of the rod M for the purpose of locating the guide wheels N so that the first turn of a layer will not be directly superposed upon the last turn of the preceding layer. By locating the wire layers in slightly staggered relation it is easier to wind the layers evenly and smoothly, especially when using a thin paper wrapping between the layers.

Turn counter

The turn counter which controls certain operations of the machine will now be described with particular reference to Figs. 2, 35 and 38 through 41. Shaft G drives worm 250 meshing with worm gear 251 driving shaft 252 journaled in bearings provided by a frame 253 mounted on frame 124. At its upper end (Fig. 41) shaft 252 carries a worm 254 driving a worm 255 mounted on a shaft 256 journaled in a bearing 257 provided by frame 253 and in a bearing 258 mounted in frame cover 259. Shaft 256 carries gear 260 meshing with a gear 261 (Fig. 42) supported by an arm 262 having a hub 263 which swings on shaft 256. Gear 261 meshes with any one of a series of gears such as 264 or 265 any one of which may be secured to a shaft 266 journaled in bearings 267 and 268 mounted in frame 253. If gear 265 is substituted for gear 264, gear 261 would be located in position 261a and would be held in that position by a clamping screw 262a passing through an arcuate slot 262b in arm 282 and threadedly engaging the frame 253. The frame 253 provides a gear housing 269 covered by a plate 270.

The inner races of bearings 267 and 268 are spaced by a sleeve 271. The outer race of bearing 267 is retained by a plate 272. The outer race of bearing 268 is spaced by a sleeve 273 from the inwardly turned annular flange 274 of a dial plate 275 secured to frame 253. The tightening of a nut 276 on shaft 266 holds the inner races of the bearings and the sleeve 271 clamped against a shoulder 277 on shaft 266. Shaft 266 is threaded at its lower end (Fig. 41) and receives a nut 278 which retains upon the shaft 266 a washer 280, a plate 281 and the hub 282 of a pointer 283 which is secured to the plate by screws 284. In order to provide access to the screws 284 the plate 281 is provided with holes 284a. The plate 281 is engaged by a spring 285 confined in a state of compression between the plate 281 and the nut 276. Spring 285 forces the plate 281 against the washer 280 which is driven by the shaft 266 by means of a cross pin 286 engaging cross slots in the washer 280. Thus the plate 281 is driven frictionally by the shaft 266 through the coaction of

said plate with the shaft driven washer 280 against which it is urged by the spring 285.

The plate 281 supports a stud 290 which is adjustable along the periphery of the plate 281. 5 For purpose of this adjustment the plate is provided with an arcuate slot 291 into which a shank of reduced diameter of the stud 290 may extend to receive a nut 292 located in the groove 293 provided by the plate 281. The direction of rotation 10 of the plate 281 is clockwise as indicated by arrow 294. During rotation of plate 281 the stud 290 engages the beveled surface 295 of lever 296 attached to shaft 297 journaled in a bearing boss 298 carried by an arm 299 extending from the 15 frame 253. Boss 298 carries a pair of screw tapped ears 300 for receiving stop screws 301 for limiting the movement of the lever 296. Referring to Fig. 40, shaft 297 is drivingly connected with a yoke member 303 having screw tapped 20 arms 304 for receiving stop screws 305 secured in adjusted position by lock nuts 306. These screws 305 determine the position of lever 296 relative to an arm 307 loosely mounted on shaft 297. The arm 307 is connected by a clevis 308 25 with a rod 309 which is connected with a control which will be described later. For the purpose of presenting understanding, it will be sufficient to say that at the end of the winding of a layer of wire of predetermined number of turns, the stud 30 290 engages the lever 296 to move the same upwardly and to cause clockwise rotation of lever 307 as viewed in Fig. 38 or counterclockwise as viewed in Fig. 40 in order to cause the clutch C (Fig. 68) to be disengaged so that the primary drive between the power source and the arbor H will be disconnected.

Coil winding layer equalizer

The elevation of the lever 296 for the purpose of 40 stopping the winding of wire is controlled by a mechanism for equalizing the disposition of the layers of windings. This equalizing mechanism is intended to overcome any tendency to shift the layers too far in any one direction longitudinally 45 of the arbor H. The clamp bracket 225 which supports the left end of the rod M (Figs. 2, 32 and 35) moves horizontally between two stop screws 310 adjustably supported by bell crank levers 311 pivoted on screws 312 carried by a bracket 313. The adjacent ends of the levers 311 are connected together by a bifurcated coupling 314 and a rod 315 with a bifurcated block 316 which straddles a lever 317 fastened to a shaft 318 journaled in a bearing 319 provided by the bracket 313. A shaft 318 carries a lever 320 connected by pin 321 with a bar 322 having a notch 323 at its upper end for receiving a pin 324 carried by lever 296. The block 316 which straddles the lever 317 is operatively connected with said lever by providing the lever with a pin 317a which engages notches 325 in block 316 said notches being offset laterally upwardly from horizontal notches 326. If the wire guide wheel supports rod M should move too far in either direction the clamp bracket 225 will, due to engagement with one of the screws 310, cause the bell crank levers 311 to move the block 316 such a distance toward the front of the machine that the bar 322 will move upwardly and cause the bottom of its notch 323 to engage the pin 324 and move the same upwardly in order to move the lever 296 upwardly for the purpose of stopping the machine. During this movement of the block 316 toward the front of the machine for the purpose of interrupting the primary drive between the power source and

the arbor, the block 316 automatically becomes disconnected from the pin 317a due to the fact that, as the block 316 so moves, its beveled surface 316a engages a roller 327 mounted on a bracket 328 adjustably secured to the bracket 313. A spring 330 connects bracket 313 with arm 320 to urge the same downwardly so that the lever 317 will normally engage a stop screw 331 threadedly passing through an ear 332 of bracket 313 and held in desired position of adjustment by a lock nut 333. Thus the normal position of the lever 317 with respect to the block 316 and the bar 322 with respect to the pin 324 is reestablished. A spring 334 (Fig. 32) connects one of the bell crank arms 311 with bracket 313. Thus the spring 334 resists movement of the bell crank arms through the coaction of clamp bracket 225 of rod M with either of the stop screws 310. Spring 334 therefore yieldingly urges block 316 toward the right as viewed in Fig. 38 so that pin 317a will normally be received by the notches 325 provided by the block 316. Therefore the bell cranks 311 are normally connected with lever 317; but the block 316 is automatically disconnected at the end of movement of lever 317 such as causes lever 296 to move far enough to stop the machine. This disconnection is effected as stated before by the co-operation of roller 327 with the block 316.

Overtravel safety stop

Referring to Fig. 34, screw threaded rods 335 and 336 mounted for horizontal sliding movement on walls 122 and 123 of the frame 124 are pivotally connected at 337 and 338 respectively with a lever 339 mounted on a shaft 340. The lower end of shaft 340 (Fig. 43) supports a lever 341 connected by a link 343 (Fig. 34) with a bell crank lever 344 pivoted at 345 and connected with a link 346 extending toward the rear of the machine. Pairs of nuts 347 and 348 are respectively mounted on screws 335 and 336 and are tightened against each other in the desired position of adjustment. The lever 170 which carries the nut sections 168 and 169 (Fig. 33) is provided with an extension 349 which is movable in the planes of movement of the nuts 347 and 348. If the mechanism associated with the turn counter P should fail to stop the machine at the end of a winding layer, then one or the other of the pairs of nuts 347 and 348 will be engaged by the lever 170 which would result in counterclockwise rotation of levers 339 and 343 and a movement of the link 346 toward the front of the machine. As will be described in detail later, this movement of the link will effect an opening of the clutch C to disconnect the arbor and feed screws from the primary drive of the machine, thereby disconnecting the clutch and interrupting the primary drive between the source of power and the arbor and feed screws.

Secondary drive

Referring to Fig. 34, the shaft B drives a worm 350 in gear box Q. Worm 350 drives a worm wheel 351 fixed to shaft 352 driving a worm 353 meshing with a worm wheel 354 which drives shaft R. Shaft R comprises a section 355, a coupling 356, a shaft 357, coupling 358 (Fig. 7) and a section 359. Section 355 is journaled in bearings 360 provided by gear box Q, and section 359 is journaled in a bracket 361 supported by the plate 125 which is supported by table 106. As shown in the diagram Fig. 68, Fig. 7 shows that shaft section 359 drives gear S meshing with gear T which may be connected by a one-revolution clutch U with a shaft 362 connected with sprocket

5 wheel V. Sprocket V is connected by sprocket chain W with sprocket wheel X which is journaled on shaft Z and may be connected therewith by a clutch Y when it is desired that the shaft Z shall be power driven through the secondary drive.

10 The shaft Z which extends across the machine parallel to the arbor H and immediately behind the arbor is supported at its right-hand end with bracket 364 (Fig. 7) and at its left-hand end by bracket 365 (Fig. 34). Fig. 34 shows that the shaft Z drives a gear HH meshing with gears II and LL. Gear LL is journaled on shaft section G-1 (Fig. 44) and is connected therewith by 15 clutch MM, one part of which is integral with gear LL and the other part of which is provided by a grooved collar 366 slidable on shaft G-1 and splined thereto by key 367. Collar 366 receives studs 368 (Fig. 43) carried by arms 369 of a yoke 370 pivoted on a rod 371 supported by a pedestal 372 integral with bracket 130. A spring 373 (Fig. 34) connects arm 369 with a pin 374 carried by bracket 130. Spring 373 therefore urges the yoke 370 counter-clockwise to engage the clutch 20 LL. In order to disengage the clutch LL the gear HH is provided with cams 375 and 375a which will contact with roller 376 carried by yoke arm 369 when the gear HH is in certain positions. Gear HH will remain in the position for locating 25 cam 375 in contact with roller 376 during the time when the arbor H is connected with the power source through the primary drive. When the primary drive is disconnected and the secondary drive to the arbor is connected so that the gear HH is rotated by shaft Z, then the cam 375 rotates out of contact with roller 376 to permit spring 373 to engage clutch LL. The control of the secondary drive is such that gear HH will move one complete revolution and then stop. 30 Gear HH will stop with cam 375 engaging roller 376 so that the secondary drive to arbor HH is disconnected at the end of one revolution of shaft Z. During rotation of gears HH the cam 375a engages the roller 376 for a time sufficient to prevent rotation of arbor H while the paper wound 35 thereon is being sheared from the supply.

30 Gear II is journaled on shaft KK which extends parallel with shaft Z and is journaled in a bearing provided by bracket 365 (Fig. 34) and in a bearing provided by bracket 364 (Fig. 7). Gear 40 II provides one part of clutch JJ, the other part being provided by a sleeve 380 slidable on shaft KK and connected therewith by a pin 381 in the shaft received by notches 382 in the sleeve 380. A spring 383 tends to engage the clutch JJ, but it will not be engaged while a flange 384 of sleeve 45 380 engages a cam 385 on gear HH (Figs. 34 and 43). Cam 385 is arcuate in formation and extends for about 270° around the periphery of the gear HH. There is therefore about 90° between the ends of the cam 385 as shown in Fig. 43. The cam 385 is so timed that shortly after the gear HH begins to rotate clockwise, the cam 385 will leave the flange 384 to permit the spring 383 to engage the clutch JJ so that shaft KK will be rotated by shaft Z during about 90° of rotation thereof.

50 Shaft KK carries a steel roller 390 provided with a soft rubber covering 391 for engaging a strip of paper 392 leading from a paper supply roll 393 (Fig. 11) which is mounted on a tube 394 which is supported by metal discs 395 threaded on a rod or shaft 396 (Fig. 35). Shaft 396 is journaled in ball bearings 397 received by cylindrical recesses 398 provided in brackets 399.

55 As shown in Fig. 11, the paper strip 392 passes

between a rubber-covered steel roller 390 and an idle pressure roller 400 which is mounted on arms 401 connected with rods 402 journaled in extensions 403 of brackets 364 and 365. Pressure roller 400 is provided with annular bosses 405 (Fig. 14) near the ends thereof (see also Figs. 8 and 36). These bosses rest upon the paper strip near the edges thereof and press the edges firmly against the rubber covering 391 of the power-driven feed roller 390. This action tends to keep the paper strip free of wrinkles. As shown in Figs. 8, 9 and 36 the pressure roller 400 has been thrown back out of operating position. In this position it is held by its own weight which maintains studs 406 carried by arms 401 in engagement with brackets 364 and 365. Figs. 16, 18 and 11 show the pressure roller 400 in operating position.

After passing between the rollers 390 and 400, the paper strip 392 passes over a guide plate 410, under a guide plate 411 and between a stationary shear bar 412 and a movable shear bar 413. As the strip 392 moves toward the arbor, the leading edge of the strip is engaged by the wires 920 and is directed between the wires and the arbor H. While the roller 390 is power-driven through the secondary drive to feed the strip 392 toward the left, the arbor H is being rotated by the secondary drive to wind the strip upon the arbor. The mechanism is constructed so that the arbor will rotate about 3 turns while winding paper thereon. Just before completion of the wrappings of 3 turns of paper upon the arbor, the shear blade 413 is caused to descend upon the paper and shear it off upon the stationary shear bar 412. Bar 412 is supported by brackets 364 and 365 (see Figs. 13 and 14). Shear bar 413 is secured at its ends to blocks 415 which are vertically slidable upon rods 416 attached to brackets 364 and 365 respectively. The upper ends of rods 416 are threaded to receive nuts 417 which confine washers 418 against compression springs 419 tending to force the blocks 415 downwardly. As shown in Figs. 16 and 18, each block 415 carries a trunnion block 420 pivotally supporting a roller 421 resting on a cam 422 keyed to the shaft Z. Once during each revolution of shaft Z the cams 422 permit the roller 421 and the blocks 415 to descend under the action of springs 419 to cause the paper strip to be sheared by the coaction of blades 413 and 412. The dwell or the high land on the cam is of such angular length that the shear blade 413 will be held above the blade 412 for a time sufficient to permit the 3 turns of paper to be passed between the shear blades. The blocks 415 are tied together by the angle bar 425 carrying nuts 426 (Fig. 14) which receives screws 427 the heads of which determine the spacing between the blade 413 and the bar 425. Blade 413 is yieldingly urged against the heads of the screws 427 by springs 428 surrounding screws 429 passing through holes in the bar 413 and engaging nuts 430 secured to the bar 425. The ends of the blade 413 are held against the blocks 415 by screws 431 (Fig. 11) surrounding screws 432 which pass through the ends of the bar 413 and through the blocks 415. Springs 431 are confined between the blocks 415 and nuts 433 attached to screws 432. The springs 431 tend to move the nuts 433 toward the right (Fig. 11) and thus cause the heads 432a of the screw 432 to bear yieldingly against the ends of the blade 413. The blade 413 is thus yieldingly urged by the springs 428 and 431 into a plane coincident with the front face of the blade 412.

During one revolution of the shaft Z clockwise as viewed in Fig. 11 the paper feed roller 390 is rotated to cause the paper strip 392 to be fed toward the arbor H and the arbor H is rotated to wind the paper thereon as it is being fed. While the paper is being sheared by blades 412 and 413, both the paper feed roll and the arbor stop rotating during the time when cam 375a (Fig. 43) is engaging roller 376. After the paper has been sheared, the arbor rotates again to wind up the length of paper between the arbor and the shear blades. Then shaft Z stops rotating due to the automatic opening of the clutch U.

During each rotation of the shaft Z the feed nut shifting cam PP is rotated 180°. This is effected through 2-to-1 ratio gears 440 and 441 (Fig. 34) the former being mounted on and driven by shaft Z and the latter being attached to shaft 42 mounted on bracket 443 and supporting and driving the cam PP. Therefore the function of feeding paper to the arbor, severing it from the supply strip and winding it upon the arbor is performed through the secondary drive while the cam PP is being rotated to shift the feed nut lever 170 between the feed screws I and J.

The secondary drive to the paper feed roll, paper shear, winding arbor and feed nut shifting cam is operated while clutches U and Y are closed.

Clutch U

The construction and operation of clutch U will now be described with reference to Figs. 20, 21, 22 and Fig. 7. The shaft 362 by which the sprocket wheel V is driven loosely supports the gear T and is supported not only by bracket 361 but also by bracket 450 which is mounted directly on the table 106. The hub of gear T is connected with a ratchet 451 having a plurality of equi-spaced notches 452, one of which is shown in Fig. 22. One of these notches is adapted to receive lug 453 on a pawl 454 pivoted at 455 on a disc 456 which is attached to the shaft 362. A spring 457 is attached to an apertured ear on the lower end of pawl 454 and to a stud 458 and the disc 456 tends to urge the lug 453 into one of the notches of the ratchet 451. In the non-operating condition of the clutch, the upper arm of the lever 454 is engaged by a locking pawl 459 which prevents engagement of the lug 453 with the ratchet 451. The locking pawl is pivoted at 460 upon an arm 461 of bracket 450 and engages a notch 462 in disc 456, thus holding the disc and the shaft 362 in a fixed position while the clutch U is open or non-operative. The pawl 459 is urged into locking position by spring 463 surrounding a rod 464 pivotally attached at 465 to a weight 466 also pivoted at 460. The rod 464 passes through a block 467 pivotally connected with pawl 459. The rod 464 is threaded to receive nuts 468, the adjustment of which determines the position of the weight 466 relative to the pawl 459. The weight 466 is normally held in the position shown in Fig. 22 by a latch 470 engaging a notch 471 provided in the weight 466. When the weight is so held by the latch 470, the spring 463 will be held in a state of compression whereby it urges the pawl 459 into locking position. In order to release the weight 466 it is necessary to retract the latch 470. Latch 470 is mounted on a shaft 472 journaled in an arm 473 of bracket 450 and carrying an arm 474 carrying a pin 475 received by a slot 476 in a plate 477 connected by rod 478 with a clevis 479 connected

by pin 480 with a lever 481 pinned to a shaft 482. By a control device to be described later, when the primary drive between the arbor H and the power source is interrupted automatically at the end of the winding of a layer of wire, the shaft 482 is caused to rotate clockwise as viewed in Fig. 20 to move the rod 478 upwardly to cause the lever 474 to rotate counter-clockwise and thus to retract the latch 470 from the weight 466, whereupon weight 466 will descend and will pull the rod 464 with it, thereby causing a nut 468 to push against the block 467, thereby causing the locking pawl 459 to be retracted from engagement with the pawl 454 and the disc 456. The spring 457 is then free to move the pawl 454 to engage with the ratchet 451, thereby connecting the ratchet 451 which is constantly rotating with the shaft 362. Then the sprocket wheel V is connected with the gear T which is driven by the gear S from the shaft R. Power is then transmitted from sprocket V to chain W to sprocket X on shaft Z. To keep chain W tight, an idler W1 is provided to engage the chain. Idler W1 is mounted on a bracket 481' adjustably on bracket 361 (Fig. 21). If clutch Y is closed, shaft Z will rotate. Sprockets V and X have the same pitch diameter so that during each revolution of shaft 362 there will be one revolution of shaft Z. Shaft 362 stops rotating exactly at the end of one revolution due to the automatic disconnecting of the clutch U. This is effected by the coaction of a roller 456a mounted on disc 456 with the lower surface of the weight 466. Disc 456 rotates clockwise as viewed in Fig. 20. By the time that the shaft 362 is near the end of one revolution, the roller 456a will engage the weight 466 to move the same upwardly, thereby causing the end of the pawl 459 to be yieldingly urged by spring 463 against the smooth periphery of the disc 456. When the notch 462 of disc 456 registers with the hooked end of bar 459, this end will quickly snap into the notch 462 and at the same time it will engage pawl 454 to disconnect it from the ratchet 451. After the weight 466 has thus been elevated to locking position it will be retained in this position by the latch 470 which, prior to this time, has been made free to descend into contact with the weight 466 because the lever 481 has previously been returned to its lower position, as will be explained later in connection with a detail description of the main control cam UU. Spring 475a, attached to pin 475, urges lever 474 clockwise to cause latch 470 to return into engagement with weight 466. It is, therefore, apparent that the clutch U permits the transmission of power from the source through the secondary drive to the sprocket X on shaft Z only for one revolution, and it will be explained later that the initiation of this cycle of operation is controlled by the main control cam UU.

Control of the clutch Y

The clutch Y is a simple tongue and notch clutch comprising a notch 490 provided by the hub of sprocket X and a tongue 491 provided by a grooved sleeve 492 slidable along shaft Z and splined thereto at 493. The grooved sleeve receives pin 494 extending from the arms 495 of a yoke 496 fixed to a shaft 497 supported by a bracket 498 located on the plate 125 (see Figs. 16 and 18). Shaft 497 carries a lever 499 connected by pin 500 with a clevis 501 connected by rod 502 with a clevis 503 (see Fig. 61) connected by pin 504 with pedal lever 505 (7 of Fig. 68) piv-

totally supported by rod 506 attached at its ends to angle bars 507 extending between the legs 508 which support the table 106. A spring 509 attached by hook to the rod 502 and to the under-side of the table 106 urges the rod 502 upwardly, thereby urging the clutch Y into closed position. The clutch Y is therefore opened by depressing the pedal 505. In order that the clutch Y may be held open without requiring the operator to keep his foot on the pedal 505, there is provided a means for locking the pedal 505 down.

Means for locking pedal 505 down to maintain clutch Y open comprises a lever 511 (7 of Fig. 68). Referring particularly to Figs. 20 and 23 lever 511 is attached to a shaft 512 journaled in a bracket 513 secured to the under side of table 106. Shaft 512 is attached to an arm 514 carrying a hard metal wearpiece 515 having a notch 516. Arm 514 is urged toward the left into engagement with a bar 525 by spring 517 encircling a rod 518 connected with arm 514 and passing through a plate 519 attached to bracket 513.

Nuts 520 on rod 518 limit the movement of arm 513 to the left by engaging plate 519. Spring 517 is confined between plate 519 and a shoulder 521 on rod 518. Spring 517 therefore urges arm 514 against the bar 525. Bar 525 is provided on the front end of lever 526 pivotally supported by rod 527 carried by bracket 528 supported by rod 529 (Fig. 57) supported at its ends by angle bars 530 extending between table legs 503. Lever 526 is connected by pin 531 with clevis 532 connected by rod 533 with clevis 534 connected by pin 535 with pedal 505 (7 of Fig. 68). When pedal 505 is moved downwardly to disconnect clutch Y, the lever 526 will be rotated counter-clockwise upon the rod 527 and the top surface of the bar 525 will be brought into alignment with the notch 516 of plate 515 whereupon the spring 517 will move the arm 514 toward the left so that the plate 515 will rest upon the bar 525 and maintain lever 526 and pedal 505 in position for retaining clutch Y in open position.

It is desirable at certain times in the use of the machine to disable the automatic winding of paper upon the arbor and to use only the handwheel AA (Fig. 7) which is directly connected with the shaft Z. Therefore before using the handwheel AA the pedal 505 is depressed far enough to permit the arm 514 to snap into position to hold the lever 505 down. When it is desired to resume the power winding of paper upon the arbor through the secondary drive, the upper end of the lever 511 which extends through a slot 511a in table 106 is moved toward the left or middle of the machine in order to retract plate 516 from bar 525, whereupon spring 509 is released to pull the pedal 505 upwardly to cause clutch Y to be engaged.

The extreme right end of the shaft Z is supported by the bracket 530. Shaft Z supports bevel gear 531 which meshes with a bevel gear 532 (Fig. 20). Gears 531 and 532 are the bevel gears BB of Fig. 68. Shaft BB1 driven by gear 532 is supported by a bracket 533 mounted on plate 125 and by bracket 534 integral with the frame 535 of the layer counter CC. Shaft BB1 carries a bevel gear 536 meshing with a bevel gear 537 driving shaft 538 for operating counter CC.

Mechanism for severing paper wound on arbor

The layers of paper wound upon the arbor are intermittently severed at places indicated at 922 75 (Fig. 1) about midway between the ends of adja-

cent full length layers of wire 921. This severing is effected by applying, to the rotating paper wrapping, blades 540 which are spaced equidistant as shown in Figs. 2 and 3 and are located so that each will sever the paper at a point 922. Referring more particularly to Figs. 24 and 27 each blade 540 is carried by an arm 541 which slides along over the top of shaft Z into contact with paper wrapping 542 on arbor H. Each arm is yieldingly urged against shaft Z by a spring 543. Each arm 541 is mounted on a rod 544 and is clamped thereto by a screw 545 which cooperates with the slit clamping hub 546 of each arm. The rod 544 is supported at its ends by arms 547 fixed to a shaft 548 supported in bearings 549 which are provided by the plate 125. Shaft 548 near its right end where it is supported by a bracket 550 (Fig. 7), is connected by pin 551 with a collar 552 integral with a lug 553. Lug 553 is engaged by a screw 554 (Fig. 26), threaded through a lug 555 and locked into adjusted position by a nut 556. Lug 555 is integral with a sleeve 557 (Fig. 7) which is loosely journaled on shaft 548. Sleeve 557 carries a plate 558 integral with an arm 559 adapted to engage a stop 560 rotatable on a shaft 561 supported by bracket 562 (Fig. 26). The position of stop 560 determines the distance through which the arm 559 and hence the shaft 548 can be rotated counterclockwise and the distance the blades 540 are moved with respect to the arbor H. Obviously, this distance will be greater when the wrappings on the arbor are of small diameter and less when these wrappings are large in diameter.

The sleeve 557 (Fig. 24) is integral with a lever 563 forked at its upper end to receive a block 564 pivotally attached to lever 563 by screws 565. Rod 566 passes loosely through block 564 and threadedly receives nuts 567, the position of which determines the normal relation between the rod 566 and the block 564. The block 564 is urged against the nuts 567 by spring 568 confined between the block 564 and a nut 569 adjustable along the rod 566. The rod 566 supports a bar 570 confined between two nuts 571 and 572 threaded on rod 566. The location of these nuts fixes the position of bar 570 relative to rod 566. Rod 566 is threadedly received by a bar 573. The rod 566 and the bar 573 together provide a connecting rod between the block 564 and a crank pin 574 carried by a crank disc 575 rotatably supported by a bracket 576 mounted on table 106. By turning the rod 566 relative to bar 573 the length of this connecting rod can be varied. The rod 566 can be locked in the desired position of adjustment with respect to bar 573 by a lock nut 577. As the crank disc 575 turns, the bar 573 and rod 566 are reciprocated to cause a lever 563 to oscillate. Oscillatory movement toward the left is transmitted to sleeve 552 through the screw 554 carried by the sleeve 557 with which the lever 563 is integral. Screw 554 presses against lug 553 and causes shaft 548 to rotate counterclockwise thereby moving levers 547 and the blade carrying arms 541 toward the left to cause the blades 540 to engage the paper wrappings 542 (Fig. 24) on arbor H. Movement of the rod 566 toward the right does not produce movement to the right of the blades 540, since this movement is effected through springs 578 anchored to table 106 and to levers 579 attached to shaft 548. Thus the blades 540 are positively advanced toward the paper and are retraced by spring operation.

As stated earlier the distance which the bearings 541 can move toward the arbor H is deter-

mined by the position of a stop 560 relative to arm 559 (Fig. 26) which is attached to the lever 563. Stop 560 is rotated counterclockwise by step by step motion accompanying reciprocations of the rod 566. Referring to Figs. 24 and 25 the stop 560, a ratchet 580 and a grooved disc 581 are connected together and are rotatable upon a shaft 561. The disc 581 carries an arm 582 urged against a stop screw 583 by a helical coil spring 584 attached to disc 581 by pin 585 received by the groove in the disc 581 and anchored to the table 106 at 586. Spring 584 urges the stop 560 clockwise so that the arm 582 normally engages the stop screw 583. This is the start position of the stop 560 and is the position in which it will be most remote from the arm 590. In this position of stop 560 the arm 563 will move the greatest distance. As the diameter of the paper wrappings 542 upon the arbor H increases this distance should decrease, as will be explained later. The blades 540 are moved against the paper wrappings once for every two paper wrappings applied. Therefore the movement of rod 566 is used to move the stop 560 by a step by step motion.

Shaft 561 supports an arm 590 carrying a pin 591 pivotally supporting a pawl 592 for engaging ratchet 580. A spring 593, which connects the pawl 592 with a pin 594 on the arm 590, urges the pawl 592 toward the ratchet 580. Pawl 592 has an arm 595 which moves between stop screws 596 and 597 adjustably carried by bracket 562 and locked by nuts 596a and 597a, respectively. A spring 598 connecting pin 594 with pin 599 on bracket 562 tends to urge the arm 590 clockwise. The bar 570 on rod 566 is engaged by a pin 600 on a lug 601 integral with arm 590.

When rod 566 moves toward the left (Fig. 24), the bar 570 moves with it and pin 600 and arm 590 follow along due to the action of the spring 598 so that the arm 590 finally arrives in the position shown in Fig. 25. Before this movement had started, the pawl 592 was out of engagement with the ratchet 580 because the pawl arm 595 was then engaging the stop screw 596 which caused the pawl 592 to be pushed away from the ratchet 580. During the movement of the arm 590 from the position shown in Fig. 24 to that shown in Fig. 25 the pawl 592 moves by the action of spring 593 into contact with ratchet 580. During movement of rod 566 toward the right the arm 590 moves from the position shown in Fig. 25 to that shown in Fig. 24, and causes the ratchet 580 to be turned by the arm 590 due to the engagement of pawl 592 with the ratchet. The turning of the ratchet 580 continues until the arm 595 of pawl 592 engages top screw 596 whereupon the pawl 592 is disengaged from the ratchet. However, the ratchet 580 is locked in its new position by a locking pawl 602 supported by a shaft 603 having a bearing in an arm 604 integral with bracket 562. Shaft 603 is pinned to an arm 605 connected by a spring 606 with a stud 607 on bracket 562.

As the winding of the coil progresses the stop 560 is rotated counterclockwise by step-by-step movement in order that the distance through which the arm 559 can move will decrease as the diameter of the paper wrappings on the arbor increases. In this way the cutter blades 540 are permitted to pass into the paper wrappings on the arbor only far enough to cut those wrappings which had not been previously cut. After the coil is completed and before starting to wind new

cols upon an empty arbor the device shown in Figs. 25 and 26 which corresponds to the blade distance controlling device BD of the diagram Fig. 68 must be reset, that is, returned to its initial position. The resetting is effected by the reset lever 752 (5 in Fig. 68) which is attached to a shaft 610 pivoted on a bracket 611 which operates an arm 612 carrying a pin 613 received by a slot 614 provided in the end of a rod 615 which is connected with an arm 616 fastened to shaft 603. When lever 752 is pulled toward the operator as far as it will go or until its lug 617 moves to position 617a, the rod 615 has been moved sufficiently to disengage the pawl 602 from the ratchet 580 whereupon the spring 584 will be released to turn the cam 580 clockwise into the position shown in Fig. 26, said movement being limited by the engagement of the arm 582 with the stop screw 583.

The mechanism operated by the crank disc 575 for operating the cutter blades corresponds to the blade operating mechanism BO of Fig. 68. This mechanism is connected with the power source through the secondary drive in the following manner. Referring to Fig. 7, the shaft 359 forming a part of shaft R of the diagram carries sprocket VV₁ connected by chain VV₂ with the sprocket VV₃ having a hub 620 which corresponds to shaft VV of Fig. 68. Hub 620 (Fig. 29) is normally loosely journailed on a shaft 621 supported by a bracket 516 and driving the crank disc 575. Shaft 621 is connected with the sprocket VV₃ by a one-revolution clutch WW which is substantially identical with the clutch U. Therefore the parts of clutch WW shown in large scale in Figs. 28, 29, 30 and 31 which are identical with the parts of clutch U shown in Figs. 20, 21, and 22 are given the same reference numerals. Figs. 28, 29 and 30 show the non-operating and locked position of the clutch. Fig. 31 shows the latch 470 retracted from the weight 466 which has dropped down so that the locking pawl 459 has been retracted. The disc 456 has rotated nearly one revolution in a clockwise direction from the position shown in Fig. 30. During this movement of disc 456 the roller 482 moves into the position 482a where it begins to engage the weight 466; then it causes the weight to move into the dot dash line position 466a where the latch 470 may re-engage it as the roller 482 moves from the position 482a to position 482b corresponding to the position of the disc 456 shown in full lines. The movement of the weight from the position shown in 466 to 466a causes the pawl 459 to be urged by the spring 463 into the dot-dash line position 459a where it bears against the edge of the disc 456 and is ready to snap into locking position with respect to the disc and to move the pawl 454 out of engagement with ratchet 451 as soon as notch 462 registers with the hook end of pawl 459.

The weight latch 470 of clutch WW is retracted by means responsive to the movement of the wire-guide bar M. (Fig. 3.) When bar M moves toward the left from the position shown in Fig. 3 it carries with it a collar 625 having a lug 626 which engages a finger 627 pivotally supported on a pin 628 provided by the forked end of a lever 629 mounted on a shaft 630 supported by a bracket 631 (Fig. 24) integral with bracket 232. Shaft 630 is journailed in bearings 632 and 633 provided by the casing 800 which encloses the mechanism on the right end of the machine. Shaft 630 carries an arm 634 connected by a pin 635 with a clevis 636 connected by rod 637 with a

5 clevis 637 connected by pin 639 with a lever 640 which is connected with the latch 470. A spring 641 connects the case 800 with the lever 634 to urge the rod 637 upwardly and the latch 470 counterclockwise as viewed in Fig. 31. As the bar M is moved toward the left from the position shown in Fig. 3, lug 626 engages the finger 627 to cause the lever 629 to be raised thereby causing the shaft 630 to rotate clockwise thereby causing the lever 634, the rod 637 and the arm 640 (Fig. 24) to move down to retract the latch 470 from the weight 466, whereupon the clutch WW becomes automatically operative to cause the crank disc 575 to make one revolution and then the clutch WW is automatically disconnected just as in the case of the clutch parts previously described. Therefore, during movement of the rod M which takes place while the arbor is being rotated through the primary drive and while the paper wrappings 542 are rotating at high speed, the blades 540 are advanced far enough to cut at least two wrappings of paper. As soon as the lug 626 on collar 625 is passed to the left of the finger 627, arm 629 drops down again upon the rod M thereby causing counterclockwise rotation of shaft 630 and upward movement of arm 634 and rod 637 due to the action of spring 641 and downward movement of latch 470 to dot-dash line position 470a so that it is ready to engage the weight 466 again when the weight is moved into the position 466a.

As the layers of wire and paper wrappings are relatively thin, it is not necessary to apply the cutter blades to the wrappings after each 35 wrapping operation but only after each two wrapping operations. As the rod M moves toward the right in returning to the position shown in Fig. 3, the lug 626 of collar 625 engages the finger 627 and merely causes it to rotate on its pin 628. After the lug 626 has passed to the right of finger 627, a spring 627a returns the finger to normal position.

The blades 540 may be advanced into contact with the paper wrappings on the arbor at any 45 time by pressing pedals m (Figs. 58, 59, 61). Pedal m (650) is journailed on a pin 650a carried by bracket 651 carried by rod 506. Pedal m is connected by pin 652 with a clevis 653 attached to a rod 654 connected with a clevis 655 connected by pin 656 with a lever 657, pinned to shaft 548. Downward movement of pedal m will effect clockwise rotation of lever 548 to cause the blades 540 to move against the paper wrappings on the arbor. The pedal m is returned to 55 normal position by spring 658 attached by hook 659 to the rod 654 and by hook 660 to the table 106.

The automatic operation of the blades 540 through the secondary drive is prevented concurrently by the automatic feeding of paper. Whenever the pedal l (Fig. 68) or 505 (Fig. 61) is depressed to open clutch Y, the counterclockwise rotation of lever 526 (Fig. 20) which accompanies downward movement of pedal 505, effects 60 a retention of the weight 466 of clutch WW so that it cannot fall down, although the latch 470 might be released. This is accomplished by connecting the lever 526 by a lever 661 with a bell crank lever 662 pivoted at 663 upon a bracket 664 attached to the table 106. Lever 662 is connected by pin 665 with a clevis 666 fixed to a rod 667 attached to its upper end to a plate 668 providing a slot 669 receiving a pin 670 connected with weight 466. The slot 669 is of such length 65 as to permit the weight 466 to move into clutch 70 75

engaging position provided the lever 505 is not pushed down, or providing the plate 668 is in the normal position shown in Fig. 24. However, if the lever 505 is moved down to disengage clutch Y, it will move the plate 668 downwardly so that the upper end of slot 669 may bear against pin 670 thus preventing the dropping of weight 466. The pedal 7 or 505, therefore, when pressed and locked down by the action of lever 514 (Fig. 23) provides a safety device which will prevent power operation of the paper feed mechanism or the paper severing blades 540. Therefore, the operator is protected against actual power operation of the paper feed and blade mechanism during the time when the operator is manually winding paper upon the arbor or performing other operations manually which would require the use of hands near the arbor where the hands might come in contact with the blades as they were advanced toward the arbor by power operation.

Transfer of paper supply roll

When the paper supply roll 393, then mounted on the brackets 399 has been unwound to such extent that its diameter is that indicated by circle 393a (Fig. 11) then a fresh supply roll indicated at 393b can be placed in readiness for quick transfer to the bracket 399 after the supply paper on roll 393 is exhausted. The assembly of a paper roll 393b and a supporting shaft 396 carrying bearings 397 is mounted upon a cradle which is provided by two levers 680 mounted on a shaft 681 carried by brackets 682 supported below the table 106. Each lever 680 provides an arm 683 carrying a pin 684 providing a pivot for a plate 685 carrying a stop pin 686 which is urged against the arm 683 by spring 687 connecting plate 685 with a boss 688 on arm 683. Each arm 683 and plate 685 provide a notch 689 for receiving a bearing 397 supporting shaft 396 upon which the paper roll 393b is mounted. The shaft 681 is connected with an arm 690 connected by pin 691 with link 692 connected by pin 693 with bell crank lever 694 journaled on rod 529 and connected by pin 695 with link 696 connected by pin 697 with lever 698 pivoted at 699 upon a bracket 700 supported by rod 506. When pedal 698 is pressed downwardly the arm 680 will be caused to move from position shown in Figs. 11 and 59 to position shown in Fig. 61. In the latter position of the arm 680, the weight of the paper roll 393b overcomes the spring 687 and the paper roll with its ball bearings 397 slide from the cradle, provided by arm 683 into the recess provided at the upper ends of brackets 399. Successive positions of the roll 393b are shown at 393c and 393d in Fig. 11. The pedal 698 and mechanism operated thereby corresponds to the pedal n of the diagram in Fig. 68. Spring 695a (Fig. 59), connecting pivot pins 695 and 691, urges pedal 698 upwardly and the arms 680 back to normal position.

Paper tension device

The right end of the paper roll supporting shaft 396 is provided with a pin 706. When the shaft 396 is located upon the bracket 399, it will be in alignment with a shaft 701 (Fig. 17) supported by a bracket 702, mounted on a table 106. Shaft 396 can be coupled to shaft 601 by means of a 70 slide sleeve 703, having a recess 704 for receiving the right end of shaft 396. Sleeve 703 is splined to shaft 701 and is provided with a pair of notches 705 for engaging the cross pin 706 in the end of shaft 396. A ball 707 urged upwardly by 75

spring 708 and bearing against an apertured portion 709 of the sleeve 703 retains the sleeve in coupling position.

The shaft 701 is connected to a grooved brake drum 710 which is frictionally engaged by a strip of brake material 711 (preferably felt) fastened to a brake band 712 fixed at one end to a pin 713, supported by the bracket 702 which provides a housing for the brake. The other end of the brake band 711, is pinned at 714 to a rod 715 extending upwardly from the housing provided by bracket 702 and through a hole in its cover 716. The rod 715 extends upwardly through a bar 717 and the upper end of the rod is threadedly engaged by a pair of nuts 718. A spring 719 is confined between the nuts and the bar 717. By turning the nuts and locking them against each other, the tension of the spring 719 is manually adjusted. The drum 710 is immersed in oil at 20 the level 710a.

The machine provides other means for adjusting the compression of spring 719 in order to change the frictional pressure of the brake lining 711 upon the drum 710 and thus varying the tension on the paper as it is withdrawn from the paper roll. At a certain time during the power winding of paper upon the arbor, it has been found desirable to reduce the pressure of the brake lining upon the brake drum; and this is effected automatically during rotation of the shaft Z clockwise from the normal position shown. Shaft Z carries a cam 720 engaging a roller 721 pivoted at 722 on a lever 723 which is pivoted at 724 on a bracket 725 mounted on plate 125. Bracket 725 slidably supports a rod 726, threadedly engaging a pair of nuts 727 passing through the bracket and pinned at 728 to the lever 723. A spring 729 encircles the rod 726 and is confined under compression between the bracket 725 and the lever 723. The spring 729, therefore, urges the roller 721 against the cam 720. The nuts 727 may engage the bracket 725 and thus limit the amount of movement of the lever 723 toward the left (Fig. 16). Lever 723 is connected by pin 730 with rod 731 connected by pin 732 with two toggle links 733 and 734 which are also connected together by the same pin 732. Link 733 is connected by pin 735 with a bar 736 which is vertically slidably supported by bracket 737 attached to bracket 702 and which supports at its upper end the bar 717. The toggle link 734 is connected by pin 738 with bar 739 vertically slidably supported by bracket 740 attached to bracket 702. The lower end of bar 739 is connected by pin 741 with arm 742 journaled at 743 and connected with arm 744 connected by pin 745 with link 746 threadedly connected at 747 with a sleeve 748 slidably through an ear 749 of bracket 611. Bracket 611 provides bearings for a shaft 750 attached to a cam 751 and a handle 752. A spring 753 encircling the rod 746 and confined between a rib 754 of plate 125 and a collar 155 pinned to rod 746 urges the rod 746 toward the right and urges the sleeve 748 against the cam 751. When the cam 751 is located in the position shown in Fig. 16, the bar 717 is located in the position shown and the amount of braking resistance will correspond to the adjustment of the spring 719 for that position of the bar 717.

Assuming that the cam 751 remains stationary, it will be apparent that after each revolution of the shaft Z, the cam 720 will permit a movement of the lever 723 and of rod 731 toward the left thereby causing the toggle pin 732 to move toward the left so that the toggle links will be

broken and the bar 736 will descend thereby relieving the compression of spring 719 and decreasing the frictional pressure afforded by the brake, and thus decreasing the tension on the paper as it is being unwound from the roll. The decrease of tension is desirable while the leading edge of the paper is being presented to the arbor for winding thereon. After starting to wind the paper upon the arbor, the tension is restored to normal.

At other times during the manufacture of coils, it may be desirable to increase the tension on the paper above the normal tension. This is desirable especially when placing the final wrapping of paper upon the coils. Therefore, the lever *j* or 752 which is used to reset the mechanism BD for controlling the distance of blade movement operates a mechanism associated with the cam 751 for increasing the tension of spring 719. When lever *j* is moved from the position shown in Fig. 16 to that shown in Fig. 10, for the purpose of providing automatic reset of the blade distance control, the cam 751 is moved from the position shown in Fig. 16 to that shown in Fig. 19, thereby causing the sleeve 741 to be moved toward the left thereby causing the bar 739 to move up and push the toggle links upward while still in a straight condition and thereby cause the bars 736 and 711 to move up to increase the compression of spring 719. Thus the pressure of the brake lining 711 upon the drum 710 will be increased to cause the tension on the paper to be increased as it is pulled from the supply roll 393. Before the work is in such condition that the automatic winding of wire and paper on the arbor may be carried on continuously, the lever *j* is returned to the position shown in Figs. 16 and 8 so that the tension of the spring 719 will be decreased to the normal tension.

Control of main clutch C

As stated earlier, clutch C comprises a friction disc 115 engageable with one side of a pulley D loosely journaled on shaft 110 or B. Disc 115 is mounted on plate 116 having a flange 117 splined to shaft B by keys 118 (Figs. 46 and 34). Sleeve 117 supports the inner race 760 of a ball bearing 761 having an outer race 762 mounted within a clutch shifter ring 763 connected with pins 764 which are screw-threadedly connected with the arms 765 of a clutch shifter yoke having a hub 766 pinned at 767 to a shaft 768. A pin 769 connects a hub 770 with a shaft 768. Hub 770 is integral with an arm 771 connected by pin 772 with a toggle link 773 connected by pin 774 with a toggle link 775 connected by pin 776 with an arm 777 integral with a hub 778. Hub 778 is loosely journaled on shaft 768 and is provided with an arm 779 carrying a screw 780 (Fig. 60), the shank of which is engageable with an arm 781, the hub 782 of which is loosely journaled on the reduced portion 778a of hub 778. Link 775 carries a weight 775a which tends to straighten out the toggle links 775 and 773 and thus hold the arms 771 and 777 at a maximum distance apart. The hub 778 which is loosely journaled on shaft 768 is provided with a downwardly extending boss 783 which is attached to a rod 784 connected by springs 785 with a main control lever for 794 (Fig. 58). Springs 785 are opposed by a spring 784a attached to rod 784. When the main control lever 794 is not in operating position (Fig. 58) spring 784a overcomes springs 785 and causes rod 784 to move counterclockwise (Fig. 47). When lever 794 is in oper-

ating position (to the right of the position shown in Fig. 58), springs 785 are stretched sufficiently to overcome spring 784a and thereby cause rod 784 to be urged clockwise around shaft 768 (Fig. 47). Under these latter conditions, when the toggle links 775 and 773 are straight, motion will be imparted to the arm 771 from the arm 777 to cause 771 to move clockwise and to act through the shaft 768, the shifter yoke 765 and the collar 763 to urge the friction disc 115 against the pulley D thereby engaging the clutch C. Movement of arm 771 clockwise by the springs 785 is resisted by a spring blade 787 which is fastened by a screw 788 to a bracket 789 mounted on table 106. The free end of blade 787 is received by pins 790 provided by arm 771. Spring 787 is biased upwardly.

It is therefore apparent that clutch C can be opened by the release of tension on the springs 785 because the spring 784a would then be free to urge the arm 771 counterclockwise and thus cause a separation of disc 115 from pulley D. Springs 785 (Fig. 58) are connected between the rod 784 and a lever 791 pivoted at 792 on the underside of the table. Lever 791 is connected by link 793 with the lever 794 corresponding to lever *j* (Fig. 58). Lever 794 is pivoted at 795 and extends through an opening 796 in the table at the front of the machine. Lever 795 is connected at 797 with interconnected toggle links 798 and 799, the latter being pivotally connected at 800 with the table 106. A spring 801 connects link 799 with a stationary part. In the position of lever *j* or 794 (Fig. 58), the springs 785 are practically untensioned so that the spring 784a operates to open the clutch C. When lever *j* or 794 is moved toward the right in Fig. 58, lever 791 will move clockwise to stretch the springs 785 which will cause rod 784 to move toward the left in Fig. 47 and cause arm 771 to act through the toggle links 775 and 773 to move arm 771 into position for closing clutch C against the action of spring 784a. Lever 794 is held in clutch closing position due to the fact that the toggle links 798 and 799 are straightened out by the action of spring 801. As stated earlier in connection with Fig. 68, when a predetermined number of layers are wound upon the arbor or when a wire connected between the arbor and a supply reel breaks, solenoid *b* is energized and its plunger *c* is caused to break the toggle links 798 and 799, whereupon the stretched springs 785 and 784a cause the handle 784 to return to the position shown in Fig. 58 and whereupon the spring 784a is free to move the arm 771 counterclockwise in order to open the clutch C.

The toggle links 798-799 may be disaligned at will by movement downward (in Fig. 58) of the hooked end 798a of a rod 798b connected with a hand grip lever 798c pivoted on lever 794 and urged counterclockwise by springs 798d. By squeezing lever 798c toward lever 794 the hooked end 798a engages toggle 798 to effect the disalignment toggles 798-799. Then lever 794 can be returned to non-operating position shown in Fig. 58 to allow spring 784a to open clutch C.

Although the handle 794 (Fig. 58) may remain in position tending to maintain the clutch C closed and engaged, the clutch C may be disengaged by the breaking of the toggle links 773 and 775, Fig. 47. These links may be broken or thrown out of alignment in response to such abnormal movement of the lever 170, through the action of feed screws I or J as to cause the lever lug 349 (Fig. 33) to engage one or the other of pairs of

nuts 347 or 348 (Fig. 34) and to cause a movement of link 346 toward the front of the machine. Fig. 46 shows link 346 connected with an arm 805 connected with a shaft 806 which is connected with an arm 807, the end of which is located vertically below a rod 808 which is slidably supported by the arm 777 and which is provided with a head 809 adapted to engage the underside of link 775. Movement of rod 346 toward the right, Fig. 46, resulting from the engagement of the lug 349 of lever 170 with either of the pairs of nuts 347 or 348 of Fig. 34 will result in an upward movement of the rod 808 to cause the toggle links 775 and 773 to be moved into the position shown in Fig. 49. When this condition exists, the spring 787 is free to move the arm 771 upwardly to cause the clutch C to open. The clutch C can be closed again provided the toggle links 773 and 775 are straightened out again by effecting a counterclockwise movement of arm 777 as shown in Fig. 50 to permit the weight 775a to straighten out the toggle links. This counterclockwise movement of arm 777 (Fig. 50) is effected by returning the main control lever 794 to nonoperating condition, by gripping lever 798c and moving both levers 794 and 798c together toward the right (Fig. 58). This reduces the force of springs 785 and permits spring 784a to move the rod 784 counterclockwise. Then the weight 775a realigns the toggle links 773 and 775. After these toggle links are realigned, the lever 794 is returned to operating position (Fig. 58), thereby causing the parts 777 and 771 to be moved from the position shown in Fig. 50 to that shown in Fig. 47.

The opening of the clutch C which results from the lifting of the plunger 808 in response to abnormal travel of the nut lever 170, is an emergency feature only and will not operate when the machine is properly adjusted. The mechanism which lifts the plunger 808 normally remains idle but may operate in an emergency to protect the machine in case it has not been properly adjusted so that movements of the wire guide wheel rod M will stop before the nut lever 170 strikes a stationary part of the machine.

Mechanism for controlling clutch C in response to winding of a layer of wire

The link 309 associated with the turn-counter B is connected at 810 (Fig. 55) with a lever 811 pivoted at 812 on a plate 813a fastened to a bracket 813 which is fastened to a bracket 814 mounted on the plate 105. Brackets 813 and 814 provide for the guidance of a vertically slidable bar 815 having a notch 816 which normally receives a latch 817 urged against the bar 815 by spring 818 connected with the bracket 813 by screw 819 and with the latch 817 by stud 820. Latch 817 is round and is prevented from turning by a pin 817a. At the end of the winding of predetermined number of turns of wire in a single layer, the turn counter arm 296 (Fig. 39) is lifted, thereby causing the rod 309 to move toward the left in Fig. 54 thereby retracting latch 815 from notch 816 thereby permitting bar 815 to descend under the action of a spring 821 which encircles a screw 822 and is confined between the head of the screw and a plate 823 through which the screw extends, said plate 823 being screwed to the upper end of the bar 815. As bar 815 descends, it moves with it an arm 824 connected at 825 by pin and slot connection with a lever 826 pivoted at 827 upon a pair of ears 828 provided by arm 771. Therefore, when the bar 815 drops, that

portion of the lever 826 which is under the link 773 as indicated at 826a, moves upwardly to cause the link 773 to move in position shown in Fig. 47 to that shown in Fig. 49, thereby permitting the spring 787 to move the arm 771 upwardly to open the clutch C.

Main control cam UU for effecting the automatic application of paper to the arbor and thereafter effecting the closing of clutch C

When bar 815 descends, it carries with it a pin 830 received by a slot 831 in a lever 832 pivoted at 833 upon bracket 813 and connected with an arm 834 carrying a pin 835 received by a slot 836 in a clevis 837 adjustably connected with a link 838 ending in a clevis 839 connected by pin 840 with a latch 841 pivoted on a screw 842, fastened to plate 105. Spring 841a, connecting pivot 842 with rod 838, urges latch 841 counterclockwise against weight 466 (Fig. 53). The latch 841 controls the action of a one-revolution clutch SS which operates on the same principle and is made of parts similar to clutches U and WW, said similar parts being identified by the reference numbers applied to the clutches U and WW. It will be seen, latch 841 normally engages a notch in weight 466 and that latch 459 normally engages a notch in disc 456 and normally maintains a pawl 454 out of engagement with a ratchet 451. Ratchet 451 (Fig. 52) is loosely journaled on a shaft 850 mounted in bearings 851 mounted in a boss or sleeve 852 integral with bracket 814. Shaft 850 is driven by the disc 456 when the pawl 454 thereon is connected with ratchet 451. Ratchet 451 is journaled on shaft 850 but is not directly connected therewith but it is directly connected with a worm wheel 853 driven by a worm 854 on the shaft 352 (Fig. 34). Shaft 352 being driven by a shaft B through the gearing 350 and 355. Shaft 352 is journaled in a bearing not shown in the gear box Q and also in a bearing 855 provided by a part 856 of bracket 813. The part 856 provides for the pivotal mounting at 857 for the latch 459 and the weight 466. As weight 466 cannot move by gravity toward the shaft 850 and it cannot operate like a weight as it did when used in clutches U and WW, weight 466 is connected by a spring 858 (Fig. 53) with a stationary part. Spring 465a urges part 466 toward shaft 850. It will be apparent from the description previously given of clutches U and WW, that the retraction of latch 841 responsible for the movement of the bar 815 under the action of spring 821 to cause clutch SS to be engaged and to cause shaft 850 to turn one revolution and then cease turning because clutch SS automatically disengages itself at the end of one revolution.

Shaft 850 drives the main control cam UU (Fig. 68) which comprises a plate 860 (Fig. 51) provided with an arcuate slot 861 through which screws 862 extend for clamping to the plate 860 a cam 863 to the desired position of adjustment. Cam 863 engages a roller 864 (Fig. 54) pivoted at 865 on the upper end of a plunger 866 slidably supported by the bracket 814. Plunger 866 is connected with a rod 867 connected with a lever 868, connected with the shaft 482 which extends across the machine under the table 106 as shown in Fig. 58 and is supported by bearing brackets 482a. As described with reference to Fig. 20, shaft 482 operates an arm 481 which operates to retract the latch 470 from the weight 466 of clutch U. Therefore, during a revolution of the cam plate 860 which is counterclockwise, the cam 863 engages the roller 864 to cause the shaft 482

to rotate clockwise as viewed in Fig. 54 and clockwise as viewed in Fig. 20, thereby causing clutch Y to be engaged so that the power source will be connected through the secondary drive with the paper feed rollers, the paper shear mechanism and with the arbor to wind paper thereon fed from the supply roll and sever the paper therefrom in the manner which has been described.

While paper is being fed to the arbor and wound thereon, the cam UU continues to operate to control other devices preparatory to restoring the closing of the clutch C at the end of one revolution of the cam UU. The periphery of plate 860 provides a low land 860a, a rise 860b, a high land 860c and a descent 860d. These cam surfaces engage a roller 870 pivoted on a lever 871 which is pivoted at 872 on gear case Q. Lever 870 carries a swivel block 873 through which a rod 874 extends, said rod being threaded to receive a pair of nuts 875, the adjustment of which determines the amount of lost motion between the block 873 and the rod 874. A spring 876 located between the block 873 and a collar 877 on rod 874 operates normally to urge the rod 874 toward the left. Rod 874 is connected at 879 (Figs. 54 and 56) with a latch plate 878 by which motion is transmitted in one direction from the lever 811 to the latch bar 817. Plate 878 is pivoted on the shank of stud 820 and is provided with a notch 880 for receiving a portion of the lever 811. While the plate 878 is in the position shown in Fig. 56, when the lever 811 is moved toward the left, motion will be transmitted by the plate 878 toward the left to the latch 817 so that the latch will be retracted.

When cam UU begins rotating counterclockwise from rest position, the rise 860b pushes the roller 870 toward the right, thereby causing lever 871 to move toward the right and take up the lost motion between the block 873 and screws 875 to cause link 874 to move toward the right and pull the latch plate 878 out of the path of movement of the lever 811. In this way, latch 817 can be restored to engagement with the bar 815 regardless of the status of the lever 811 and parts of the turn counter P connected therewith. After the lifting of the lever 296 of turn counter P (Fig. 38) to cause the opening of the clutch C, the lever 296 would remain in that position until the clutch was closed again. Therefore, it is necessary to release the latch 817 from its connection with lever 811 so that the bar 815 could be latched in its upper position before reclosing clutch C. For the purpose of elevating bar 815 so that it may bring its notch 816 into alignment with the latch 817, the disc 860 is provided with cams 885 and 886 each one of which will engage a roller 887 on bar 823 and lift the bar 815. One cam 885 alone should suffice; but the extra one, numbered 886, is provided in order to make sure that the bar 815 has been restored to latched position before clutch C is reengaged.

The movement to the right by Fig. 51, of the lever 871, causes movement to the left as viewed in Figs. 49 and 50 of the arm 781 from the position shown in Fig. 49 to that shown in Fig. 50, arm 781 being connected with lever 811 by swivelled collar 890, pin 891, rod 892, clevis 893 and pin 894. This movement of the arm 781 by the lever 871 causes a movement of the arm 771 from the position shown in Fig. 49 to that shown in Fig. 50, thereby increasing the distance between the remote ends of the toggle links 773 and 775

to allow the weight 775a to straighten out the toggle links as shown in Fig. 50. The arm 781 carries a rod 895 connected by spring 896 with plate 105. The spring 896 maintains the roller 870 in engagement with the cam plate 860.

5 The roller 870 is maintained on the high land 860c of the cam plate 860 during a major portion of a revolution of the control cam UU; but when the cam surface 860d engages the roller 870, or it allows the roller 870 to reengage the low land 860a, then the lever 871 moves toward the left in Fig. 51 and toward the right in Figs. 50 and 47, thereby causing the arm 781 to move from the position shown in Fig. 50 to Fig. 47, thereby causing the clutch C to be closed again since the toggle links 773 and 775 are in alignment during the movement of lever 781 to the position shown in Fig. 47. Therefore, the cam UU has caused the clutch C to be closed before the end of one revolution of the cam UU. However, by this time, a paper wrapping has been wound upon the arbor through the operation of the secondary drive, so there is no need to delay the reclosing of clutch C until the end of one revolution of cam UU.

20 25 Movement of lever 871 toward the left in Fig. 51 as roller 870 rides down the incline 860d to the low land 860a causes the latch plate 878 to be restored to normal condition relative to the latch 817. After clutch C is reengaged and the turn counter P starts operating, the lever 296 (Fig. 38) drops below the position shown in order that the bar 309 may be moved toward the rear of the machine, thereby moving the lever 811 from the dot-dash-line position 811a of Fig. 56 to the full line position. As lever 811 thus moves,

30 35 it rides over the upper point of the plate 878 of Fig. 56, said plate 878 moving against the action of spring 876 to permit the bar 811 to return to normal position. Then the plate 878 snaps back into normal position under the action of spring 876 (Fig. 51) when the left hand edge of lever 811 is in alignment with the notch 880 of plate 878.

40 45 50 The lifting of the bar 815 causes the link 838 to move toward the right to effect counterclockwise movement of the latch 817 (Fig. 53) so it will retain the part 466 in outer position at the end of one revolution of the clutch SS. The clutch UU and control mechanisms associated therewith are restored to normal or rest condition and are ready for a repetition of the cycle of their operation to occur again at the end of

55 60 65 winding of the succeeding layer of coil turns. This cycle of operation will be repeated as long as is required to wind a predetermined number of layers of wire and paper upon the arbor. When the required number of layers have been wound upon the arbor, the layer counter CC, by closing switch a (Fig. 68) effects the energization of the solenoid b to stop the machine.

65 70 75 Referring to Fig. 59, the motor 102 is mounted on a base 900 pivoted at 901 upon a plate 902 integral with sleeves 903 which are vertically slidable on rods 904 secured by nuts 905 and 906 to the leg cross member 507. The weight of the motor 102 tends to urge the plate 900 downwardly and thus tightens the belt 100. Plate 900 is stopped by a screw 908 threaded through the plate 902 and held in adjusted position by screw 909.

Wire unreeling device

75 The mechanisms of the right and left sides of the machine are enclosed by cases 910 and 911

respectively which provide pedestals for supporting a platform 912. Platform 912 supports wire spools 913 from which the wire is unreeled by arms 914 each pivotally supported by tube 915 passing through the center of the spool 913. The arm 915 carries a guide wheel 916 around which the wire passes while being unwound, said wire indicated at 917 passing around a guide wheel 918 supported by an arm 919 pivotally mounted on a post 920 supported by the platform 912. The wire 917 is passed around a guide wheel N and then to the arbor H upon which the coils 921 (Fig. 1) have been wound.

Referring to Figs. 62 and 63, each post 920 supports a bar 925 providing a pivot at 926 for the arm 919. Arm 919 provides a pedestal support 927 for mercury switch 928. Switch 928 normally rests in a horizontal position and is held in this position by weight 929 on a rod 930 attached to switch case 928. In the position of the switch 928 shown in Fig. 62 the switch is open and is held in open position so long as a wire 17 is connected with the arbor H. The wire 17 being under tension, holds the arm 919 in the position shown in which the action of a leaf spring 930 bearing against a pin 931 attached to the arm 919. If the wire 917 should break, the spring 930 will be released to move the arm 919 clockwise and thus move the switch 928 into such position that the mercury therein can flow to bridge a pair of contacts whereupon the solenoid b (Fig. 68) will be energized to cause the machine to stop. The switch 928 may be tilted in an upright position on its pivot 927 in case it is desired to operate the machine when no wire is being wound.

Referring to Fig. 62, each spool is prevented from turning because it rests upon pointed studs 940 supported by platform 912. The tube 915, which is located within the center hole of the spool, is fastened to a bushing 941 screwed to the table 912. Within tube 915 is mounted a bearing 942 for a shaft 943, the lower end of which is threaded to receive the nut 944 for adjusting the tension of a spring 945 bearing upwardly against a flanged washer 946 which urges felt washers 947 against the lower end of the tube 943 and bearing 942. The washer 946 has a smooth fit with the shaft 943, that portion of the shaft being chrome-plated to a diameter about .004 less than the diameter of the hole in the washer 946. The upper end of shaft 943 is threaded at 950 to be engaged by a tapped collar 951 which is rotatable freely on the threads 950 although the threads 950 serve to limit the position of the collar 951 longitudinally of the shaft 943. The collar 950 has an externally tapered shank 952 around which the upper turns of a spring 953 are located and soldered thereto. The bottom turns of spring 953 are soldered to the tapered shank 954 of the collar 955 resting upon felt washers 956 supported by the upper surface of the bearing 942. Shanks 952 and 954 prevent the end turns of the coil from bending. The spring 953 is made preferably of about 130 turns of .018 inch diameter wire closely wound. After winding, the coil 953 has a normal length greater than the distance between the collars 951 and 954. Hence the spring 953 is in a state of compression between collars 951 and 954. Spring 953 functions as a roller shade spring since its lower end is frictionally engaged by the collar 955, and its upper end is frictionally engaged by the collar 951, rotation of collar 951 is yieldingly resisted by the spring 953 which tends to rotate

the collar to normal position. The spring 953 is biased in such direction as to tend to move the collar 951 counter-clockwise as viewed in Fig. 66, the front face of the collar 951 moving in the direction of the arrow 957 in Fig. 67. Movement of the collar 951 in this direction is limited by the striking of a pin 958 mounted in the collar with a lug 959 provided by a collar 960 attached by pin 961 to the reduced upper end 962 of the shaft 943.

Collar 951 is connected by integral bars 962 and 963 with a sleeve 964 having a bulbous annular bearing 965 in the interior of the tube 915. Sleeve 964 is provided adjacent its upper end with a bayonet slot 966 (Fig. 63) for receiving the arm 914 secured to a sleeve 967 received within the upper portion of the sleeve 964. Below the sleeve 967, the sleeve 964 supports a felt disc 968 supported by metal washer 969 resting on a shoulder 970 provided by sleeve 964. The function of the disc 968 is to exclude dust from the interior of the tube 915.

The bias of the spring 953 tending to rotate the arm 914 (counter-clockwise as viewed from above) may be varied by screwing the nut 944 upward along the lower end of the rod 943. By so doing, the compression of spring 945 is increased to increase the braking pressure of the washers 947 upon the stationary parts. The increase of compression of spring 945 tends to urge the shaft 943 downwardly, thus increasing compression of the spring 953. Increasing the compression of spring 953 will tend to increase its torsional effect to resist rotation of the arm 914 in a clockwise direction as well as increasing the braking pressure of the disc 968 upon the upper end of the bearing 942.

When the wire 917 starts to move from the spool 913 as the arbor H starts to turn to wind the wire thereon, the pulling of the wire 917 tends to move the arm 914 in a clockwise direction as viewed from above, thereby tending to wind up the spring 953 and thereby increasing its torsional effect. This causes the sleeve 964 and the collar 951 to rotate clockwise (as viewed from above), and to be screwed downwardly on rod 943. At the end of the first clockwise rotation of arm 914, pin 958 will be below the lug 959 of collar 960. After 4 or 5 revolutions of arm 914, pin 958 will engage lug 959a of a collar 960. Then the shaft 943 will begin to rotate, its rotation being frictionally retarded by the braking action of the washers 947 and 956 upon the ends of bearing 942. Hence such jerking of the wire as would tend to break even the finest wire is eliminated by gradually building up the resistance to the clockwise rotation of the arm 914, said resistance being increased gradually through the action of the roller shade spring 953.

When changing spool 913, the arm 914 and its sleeve 967 are removed from the sleeve 964. These are the only parts which require uncoupling in order to remove the empty spool and substitute a full one.

Directions for operating machine

Before the arbor H is mounted as shown in Figs. 1 and 3 upon the head stock and tail stock of the machine, a plurality of paper tubes 980 are passed over the arbor, the number being equal to the number of coils to be wound, this number being 10 as shown in Fig. 1. A flexible braided wire 981 had been attached to each tube 980 by staple 982 before mounting the tube upon the arbor. As each tube 980 is passed over the

arbor, a portion of the wire 981 is passed through a notch 983 provided at one end of the tube, and the wire 981 is passed within the tube and is laid within a longitudinal groove 984 provided by the arbor. The portion 981a of the wire 981 provides a key through which the arbor H drives the tube 980. The portion 981b of the wire 981 provides means for attaching the starting lead of the wire 917 to be wound upon the tube 980. The starting lead is bared of insulation so that it becomes electrically connected with the wire 981. In the construction of an ignition coil this wire 981 provides means for connecting the secondary winding of the coil with a suitable terminal.

After mounting the arbor H, the wheel AA is manually turned with the right hand while the left hand is employed to reset the layer counter CC. The wires 917 are then connected with the various flexible wire portions 981b of the tubes 980 on the arbor H. The splice of each wire 917 with each wire 981b is then taped to the tube 980. The lever J is moved toward the front of the machine in order to reset the blade distance controlling mechanism BD.

Push wheel 163 at the left of the machine inwardly to the position shown in Fig. 44 for coarse feeding of wire. Pull lever J toward center of machine to apply power and wind on one coarsely spaced layer of wire and shellac this layer.

Apply wrapping of paper by turning hand-wheel AA, and shellac.

Pull wheel 163 toward the left away from machine for fine feeding and power-wind one-half layer.

Rotate wheel AA sufficiently to feed edge of paper to arbor. Adjust wheel 163 for coarse feeding and turn wheel 163 to wind several layers of paper on arbor. Then turn wheel AA to wind on additional layers of paper and cut off. Then shellac this wrapping.

Adjust wheel 163 for fine feeding, and power-wind one layer of wire and shellac. Turn wheel AA to feed edge of paper to arbor. Rotate wheel 163 to apply one layer of paper, then turn wheel AA to wind on three layers of paper and to cut off.

Move layer J away from operator in order to reduce the tension on paper. Move layer K toward the right end of machine in order to release pedal I so that spring 509 may cause clutch Y to be engaged so that shaft Z will be connected to the power source through the secondary drive. Wind upon the arbor automatically layers of wire and layers of paper up to the predetermined number of layers of wire. The machine will automatically stop after winding the last layer of the predetermined number since the layer counter CC closes the switch a.

Operate machine by power to wind on one layer of wire and shellac this layer.

Then rotate hand wheel AA sufficiently to feed edge of paper to the arbor and wind on ten turns of paper by turning hand-wheel 163 which is still adjusted for fine feeding. Then turn hand-wheel AA to wind on three turns of paper and cut off. Then power-operate the machine to wind on 90 turns of wire, fine feed. Then shift to the coarse feed and wind on 8 turns by hand operation (or power) and shellac this final layer of wire turns. Anchor the end leads to the paper by adhesive tape and sever the wires 917. The free end of the wires 917 are passed around one of two hooks 1000 provided by two collars 1001 on the rod N. Remove the arbor H with completed windings

thereon and substitute an arbor upon which empty coil tubes 980 are mounted.

While the embodiment of the present invention as herein disclosed constitutes a preferred form, it is to be understood that other forms might be adopted, all coming within the scope of the claims which follow.

What is claimed is as follows:

1. A coil winding machine having an arbor for winding a coil of wire thereon in layers alternating with wrappings of paper, a motor, a high speed primary drive including a clutch for connecting the motor with the arbor, a mechanism for causing a paper wrapping to be wound upon the arbor, a low speed secondary drive including a clutch for connecting the motor with said mechanism, and means for controlling the clutches so that one clutch is active while the other is inactive and vice versa.
2. A coil winding machine having an arbor for winding a coil of wire thereon in layers alternating with wrappings of paper, a motor, a high speed primary drive including a clutch for connecting the motor with the arbor, a mechanism for causing a paper wrapping to be wound upon the arbor, a low speed secondary drive including a clutch for connecting the motor with said mechanism, and means responsive to the completion of a layer of wire turns for causing the primary drive clutch to be disconnected and the secondary drive clutch to be connected.
3. A coil winding machine having an arbor for winding a coil of wire thereon in layers alternating with wrappings of paper, a motor, a high speed primary drive including a clutch for connecting the motor with the arbor, a mechanism for causing a paper wrapping to be wound upon the arbor, a low speed secondary drive including a clutch for connecting the motor with said mechanism, a wire turn counter operated by the primary drive, and means responsive to a function of the turn counter for causing the primary drive clutch to be disconnected and the secondary drive clutch to be connected.
4. A coil winding machine having an arbor for winding a coil of wire thereon in layers alternating with wrappings of paper, a motor, a high speed primary drive including a clutch for connecting the motor with the arbor, a mechanism for causing a paper wrapping to be wound upon the arbor, a low speed secondary drive including a one-revolution clutch for connecting the motor with said mechanism, and means responsive to the completion of a layer of wire turns for causing the primary drive clutch to be disconnected and the secondary drive clutch to be connected, said means operating after the application of paper to the arbor to reconnect the primary drive clutch.
5. A coil winding machine having an arbor for winding a coil of wire thereon in layers alternating with wrappings of paper, a motor, a high speed primary drive including a clutch for connecting the motor with the arbor, a mechanism for causing a paper wrapping to be wound upon the arbor, a low speed secondary drive including a one-revolution clutch for connecting the motor with said mechanism, a wire turn counter operated by the primary drive, and means responsive to a function of the turn counter for causing the primary drive clutch to be disconnected and the secondary drive clutch to be connected, said means operating after the application of paper to the arbor to reconnect the primary drive clutch.

6. A coil winding machine having an arbor for winding a coil of wire thereon in layers alternating with wrappings of paper, a motor, a high speed primary drive including a clutch for connecting the motor with the arbor, a mechanism for causing a paper wrapping to be wound upon the arbor, a low speed secondary drive including a one-revolution clutch for connecting the motor with said mechanism, a control cam, a one-revolution clutch for connecting the control cam with the motor, means responsive to the completion of a layer of wire-turns for effecting disengagement of the primary drive clutch and for effecting engagement of the control cam clutch, means operated by the control cam for causing the secondary drive clutch to be engaged, and means operated by the control cam for causing the primary drive clutch to be re-engaged after the application of paper to the arbor.

7. A coil winding machine having an arbor for winding a coil of wire thereon in layers alternating with wrappings of paper, a motor, a high speed primary drive including a clutch for connecting the motor with the arbor, a mechanism for causing a paper wrapping to be wound upon the arbor, a low speed secondary drive including a one-revolution clutch for connecting the motor with said mechanism, a control cam, a one-revolution clutch for connecting the control cam with the motor, a wire-turn counter operated by the primary drive, means responsive to a function of the turn counter for causing the primary drive clutch to be disengaged and for effecting engagement of the control cam clutch, means operated by the control cam for causing the secondary drive clutch to be engaged, and means operated by the control cam for causing the primary drive clutch to be reengaged after the application of paper to the arbor.

8. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a mechanism including a pair of toggle links which when aligned, transmit force from the second force applying means to the clutch operating member to engage the clutch in opposition to the tendency of the first force applying means, and means for disaligning the toggle links in order that the first force applying means may operate to disengage the clutch.

9. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a mechanism including a pair of toggle links which, when aligned, transmit force from the second force applying means to the clutch operating member to engage the clutch in opposition to the tendency of the first force applying means, and means responsive to the completion of a layer of wire turns for disaligning the toggle links in order that the first force applying means may operate to disengage the clutch.

10. A coil winding machine having an arbor for winding a coil of wire in layers thereon, a motor, a clutch for connecting the motor with

the arbor, a clutch operating member movable to control the clutch, a first force applying means operating upon the clutch operating member and tending to disengage the clutch, a second force applying means operable to engage the clutch, a mechanism including a pair of toggle links which, when aligned, transmit force from the second force applying means to the clutch operating member to engage the clutch in opposition to the tendency of the first force applying means, means for guiding the wire evenly upon the arbor and including an arm carrying nut-segments engageable with motor driven feed screws, and means responsive to over-travel of said arm for disaligning the toggle-links in order that the first force applying means may operate to disengage the clutch.

11. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a mechanism including a pair of toggle links which, when aligned, transmit force from the second force applying means to the clutch operating member to engage the clutch in opposition to the tendency of the first force applying means, and means for reducing the amount of force exerted by the second force applying means below the amount of force exerted by the first force applying means, whereby the first force applying means opens the clutch.

12. A coil winding machine having an arbor for winding a coil of wire in layers thereon, a motor, a clutch, for connecting the motor with the arbor, a clutch operating member movable to control the clutch, a first force applying means operating upon the clutch operating member and tending to disengage the clutch, a second force applying means operable to engage the clutch, a mechanism including a pair of toggle links which, when aligned, transmit force from the second force applying means to the clutch operating member to engage the clutch in opposition to the tendency of the first force applying means, means responsive to the completion of a layer of wire turns for disaligning the toggle links in order that the first force applying means may operate to disengage the clutch, means for guiding the wire evenly upon the arbor and including an arm carrying nut-segments engageable with motor driven feed screws, and means responsive to over-travel of said arm for disaligning the toggle-links in order that the first force applying means may operate to disengage the clutch.

13. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a mechanism including a pair of toggle links which when aligned, transmit force from the second force applying means to the clutch operating member to engage the clutch in opposition to the tendency of the first force applying means, means responsive to the completion of a layer of wire turns for disaligning the toggle links in order that the first force applying means may operate to disengage the clutch and means for

reducing the amount of force exerted by the second force applying means below the amount of force exerted by the first force applying means, whereby the first force applying means opens the clutch.

14. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a mechanism including a pair of toggle links which, when aligned transmit force from the second force applying means to the clutch operating member to engage the clutch in opposition to the tendency of the first force applying means, means for guiding the wire evenly upon the arbor and including an arm carrying nut-segments engageable with motor driven feed screws, and means responsive to over-travel of said arm for disaligning the toggle-links in order that the first force applying means may operate to disengage the clutch, and means for reducing the amount of force exerted by the second force applying means below the amount of force exerted by the first force applying means, whereby the first force applying means opens the clutch.

15. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a mechanism including a pair of toggle links which, when aligned, transmit force from the second force applying means to the clutch operating member to engage the clutch in opposition to the tendency of the first force applying means, means responsive to the completion of a layer of wire turns for disaligning the toggle links in order that the first force applying means may operate to disengage the clutch, means for guiding the wire evenly upon the arbor and including an arm carrying nut-segments engageable with motor driven feed screws, and means responsive to over-travel of said arm for disaligning the toggle-links in order that the first force applying means may operate to disengage the clutch, and means for reducing the amount of force exerted by the second force applying means below the amount of force exerted by the first force applying means, whereby the first force applying means opens the clutch.

16. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a force transmitting mechanism for transmitting the force of the second force applying means to the clutch operating member, and means for rendering the force transmitting mechanism inactive in order that the first force applying means may operate to disengage the clutch.

17. A coil winding machine having an arbor for winding a coil of wire in layers thereon, a motor, a clutch for connecting the motor with the arbor, a clutch operating member movable

to control the clutch, a first force applying means operating upon the clutch operating member and tending to disengage the clutch, a second force applying means operable to engage the clutch, a

- 5 force transmitting mechanism for transmitting the force of the second force applying means to the clutch operating member, and means responsive to the completion of a layer of wire turns for rendering the force transmitting mechanism inactive in order that the first force applying means may operate to disengage the clutch.
- 10

12. A soil with decomposing organic material.

18. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a force transmitting mechanism for transmitting the force of the second force applying means to the clutch operating member, means for guiding the wire evenly upon the arbor and including an arm carrying nut-segments engageable with the motor driven feed screws, and means responsive to over-travel of said arm for rendering the force transmitting mechanism inactive in order that the first force applying means may operate to disengage the clutch.

30 19. A coil winding machine having an arbor for winding a coil of wire in layers thereon, a motor, a clutch for connecting the motor with the arbor, a clutch operating member movable to control the clutch, a first force applying means 35 operating upon the clutch operating member and tending to disengage the clutch, a second force applying means operable to engage the clutch, a force transmitting mechanism for transmitting the force of the second force applying means to 40 the clutch operating member, and means for reducing the amount of force exerted by the second force applying means below the amount of force exerted by the first force applying means, 45 whereby the first force applying means opens the clutch.

50 20. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a force transmitting mechanism for transmitting the force of the second force applying means to the clutch operating member, means responsive to the completion of a layer of wire turns for rendering the force transmitting mechanism inactive in order that the first force applying means may operate to disengage the clutch, means for guiding the wire evenly upon the arbor and including an arm carrying nut-segments engageable with motor driven feed screws, and means responsive to over-travel of said arm for rendering the force transmitting mechanism inactive in order that the first force applying means may operate to disengage the clutch.

55 60 65

21. A coil winding machine having an arbor for winding a coil of wire in layers thereon, a motor, a clutch for connecting the motor with the arbor, a clutch operating member movable to control the clutch, a first force applying means operating upon the clutch operating member and ending to disengage the clutch, a second force applying means operable to engage the clutch, a

force transmitting mechanism for transmitting the force of the second force applying means to the clutch operating member, means responsive to the completion of a layer of wire turns for rendering the force transmitting mechanism inactive in order that the first force applying means may operate to disengage the clutch and means for reducing the amount of force exerted by the second force applying means below the amount of force exerted by the first force applying means, whereby the first force applying means opens the clutch.

22. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a force transmitting mechanism for transmitting the force of the second force applying means to the clutch operating member, means for guiding the wire evenly upon the arbor and including an arm carrying nut-segments engageable with motor driven feed screws, and means responsive to over-travel of said arm for rendering the force transmitting mechanism inactive in order that the first force applying means may operate to disengage the clutch, and means for reducing the amount of force exerted by the second force applying means below the amount of force exerted by the first force applying means, whereby the first force applying means opens the clutch.

23. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a force transmitting mechanism for transmitting the force of the second force applying means to the clutch operating member, means responsive to the completion of a layer of wire turns for rendering the force transmitting mechanism inactive in order that the first force applying means may operate to disengage the clutch, means for guiding the wire evenly upon the arbor and including an arm carrying nut-segments engageable with motor driven feed screws, and means responsive to over-travel of said arm for rendering the force transmitting mechanism inactive in order that the first force applying means may operate to disengage the clutch and means for reducing the amount of force exerted by the second force applying means below the amount of force exerted by the first force applying means, whereby the first force applying means opens the clutch.

24. A coil winding machine having an arbor for winding a coil of wire in layers thereon, a motor, a clutch, for connecting the motor with the arbor, a clutch operating member movable to control the clutch, a first force applying means operating upon the clutch operating member and tending to disengage the clutch, a second force applying means operable to engage the clutch, a mechanism including a pair of toggle links which, when aligned, transmit force from the second force applying means to the clutch operating member to engage the clutch in opposition to the tendency of the first force applying

means, means for disaligning the toggle links in order that the first force applying means may operate to disengage the clutch and means driven by the motor for effecting the realignment of the toggle links.

25. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a mechanism including a pair of toggle links which, when aligned, transmit force from the second force applying means to the clutch operating member to engage the clutch in opposition to the tendency of the first force applying means, means responsive to the completion of a layer of wire turns for disaligning the toggle links in order that the first force applying means may operate to disengage the clutch and means driven by the motor for effecting the realignment of the toggle links.

26. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a mechanism including a pair of toggle links which, when aligned, transmit force from the second force applying means to the clutch operating member to engage the clutch in opposition to the tendency of the first force applying means, means for guiding the wire evenly upon the arbor and including an arm carrying nut-segments engageable with motor driven feed screws, means responsive to over-travel of said arm for disaligning the toggle-links in order that the first force applying means may operate to disengage the clutch and means driven by the motor for effecting the re-alignment of the toggle links.

27. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a mechanism including a pair of toggle links which, when aligned, transmit force from the second force applying means to the clutch operating member to engage the clutch in opposition to the tendency of the first force applying means, and means for reducing the amount of force exerted by the second force applying means below the amount of force exerted by the first force applying means, whereby the first force applying means opens the clutch, said means operating also to effect the re-alignment of the toggle links.

28. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a force transmitting mechanism for transmitting the force of the second force applying means to the clutch operating member, means for render-

ing the force transmitting mechanism inactive in order that the first force applying means may operate to disengage the clutch and means driven by the motor for restoring the force transmitting mechanism to active status.

29. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a force transmitting mechanism for transmitting the force of the second force applying means to the clutch operating member, means responsive to the completion of a layer of wire turns for rendering the force transmitting mechanism inactive in order that the first force applying means may operate to disengage the clutch, and means driven by the motor for restoring the force transmitting mechanism to active status.

30. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a force transmitting mechanism for transmitting the force of the second force applying means to the clutch operating member, means for guiding the wire evenly upon the arbor and including an arm carrying nut-segments engageable with motor driven feed screws, means responsive to overtravel of said arm for rendering the force transmitting mechanism inactive in order that the first force applying means may operate to disengage the clutch and means driven by the motor for restoring the force transmitting mechanism to active status.

31. A coil winding machine having an arbor for winding a coil of wire in layers thereon, a motor, a clutch for connecting the motor with the arbor, a clutch operating member movable to control the clutch, a first force applying means operating upon the clutch operating member and tending to disengage the clutch, a second force applying means operable to engage the clutch, a force transmitting mechanism for transmitting the force of the second force applying means to the clutch operating member, and means for reducing the amount of force exerted by the second force applying means below the amount of force exerted by the first force applying means, whereby the first force applying means opens the clutch, said means operating also to restore the force transmitting mechanism to active status.

32. A coil winding machine having an arbor for winding a coil of wire thereon in layers, a motor, a clutch for connecting the motor with the arbor, a clutch operating member, a first force applying means operating upon the clutch operating member and tending to disengage the clutch, a second force applying means capable of exerting a force greater than the force of the first force applying means, mechanism for transmitting the force of the second force applying means to the clutch operating member in a direction for engaging the clutch, means responsive to the completion of winding a layer of wire turns for rendering the force transmitting mechanism inactive so that the clutch is disengaged by the

first force applying means, a one-revolution clutch for transmitting motion from the motor and rendered active in response to the completion of a layer of wire turns, and means driven by the one-revolution clutch for restoring the force transmitting mechanism to active status.

33. A coil winding machine having an arbor for winding a coil of wire thereon in layers, a motor, a clutch for connecting the motor with the arbor, a clutch operating member, a first force applying means operating upon the clutch operating member and tending to disengage the clutch, a second force applying means capable of exerting a force greater than the force of the first force applying means, mechanism for transmitting the force of the second force applying means to the clutch operating member in a direction for engaging the clutch, a turn counter, a plunger and a spring for urging the plunger in one direction, a latch and a spring for urging the latch into engagement with the plunger for retaining the plunger against the action of its spring, a turn-counter-operated linkage connected with the latch for causing the latch to be retracted in response to operation of the turn counter, whereby the plunger is operated by its spring, a one-revolution clutch for transmitting motion from the motor, devices moved by said plunger for rendering the force-transmitting mechanism inactive and for rendering the one-revolution clutch active, and means driven by the one revolution clutch for restoring the force transmitting mechanism to active status and for restoring the plunger to normal position in which it is retained by the plunger latch.

34. A coil winding machine having an arbor for winding a coil of wire thereon in layers, a motor, a clutch for connecting the motor with the arbor, a clutch operating member, a first force applying means operating upon the clutch operating member and tending to disengage the clutch, a second force applying means capable of exerting a force greater than the force of the first force applying means, mechanism for transmitting the force of the second force applying means to the clutch operating member in a direction for engaging the clutch, a turn counter, a plunger and a spring for urging the plunger in one direction, a latch and a spring for urging the latch into engagement with the plunger for retaining the plunger against the action of its spring, a lever for moving the latch against the action of its spring, a plate for connecting the lever with the latch, a turn-counter operated linkage connected with the lever for causing the latch to be retracted in response to operation of the turn counter, whereby the plunger is operated by its spring, a one-revolution clutch for transmitting motion from the motor, devices moved by said plunger for rendering the force transmitting mechanism inactive and for rendering the one-revolution clutch active, and means driven by the one-revolution clutch for retracting the latch plate from engagement with the lever, for restoring the plunger to normal position in which it is retained by the plunger latch, for restoring the latch plate to normal position wherein it may be reengaged by the lever, and for restoring the force-transmitting mechanism to active status.

35. A coil winding machine having an arbor for winding a coil of wire thereon in layers, a motor, a clutch for connecting the motor with the arbor, a clutch operating member, a first force applying means operating upon the clutch

operating member and tending to disengage the clutch, a second force applying means capable of exerting a force greater than the force of the first force applying means, mechanism for transmitting the force of the second force applying means to the clutch operating member in a direction for engaging the clutch, said mechanism including toggle links, aligned when the mechanism is active, for connecting the second force applying means with the clutch operating member, means responsive to the completion of winding of a layer of wire for disaligning the toggle links so that the arbor clutch is disengaged by the first force applying means, a one-revolution clutch for transmitting motion from the motor and rendered active in response to the completion of a layer of wire turns, and means driven by the one-revolution clutch for realigning the toggle links.

36. A coil winding machine having an arbor for winding a coil of wire thereon in layers, a motor, a clutch for connecting the motor with the arbor, a clutch operating member, a first force applying means operating upon the clutch operating member and tending to disengage the clutch, a second force applying means capable of exerting a force greater than the force of the first force applying means, mechanism for transmitting the force of the second force applying means to the clutch operating member in a direction for engaging the clutch, said mechanism including toggle links, aligned when the mechanism is active, for connecting the second force applying means with the clutch operating members, a turn counter, a plunger and a spring for urging the plunger in one direction, a latch and a spring for urging the latch into engagement with the plunger for retaining the plunger against the action of its spring, a turn-counter-operated linkage connected with the latch for causing the latch to be retracted in response to operation of the turn counter, whereby the plunger is operated by its spring, a one-revolution clutch for transmitting motion from the motor, devices moved by said plunger for disaligning the toggle links so that the arbor clutch is disengaged by the first force applying means, and for rendering the one-revolution clutch active, and means driven by the one-revolution clutch for realigning the toggle-links and for restoring the plunger to normal position in which it is retained by the plunger latch.

37. A coil winding machine having an arbor for winding a coil of wire thereon in layers, a motor, a clutch for connecting the motor with the arbor, a clutch operating member, a first force applying means operating upon the clutch operating member and tending to disengage the clutch, a second force applying means capable of exerting a force greater than the force of the first force applying means, mechanism for transmitting the force of the second force applying means to the clutch operating member in a direction for engaging the clutch, said mechanism including toggle links, aligned when the mechanism is active, for connecting the second force applying means with the clutch operating member, a turn counter, a plunger and a spring for urging the plunger spring in one direction, a latch and a spring for urging the latch into engagement with the plunger for retaining the plunger against the action of its spring, a lever for moving the latch against the action of its spring, a plate for connecting the lever with the latch, a turn-counter operated linkage connect-

ed with the lever for causing the latch to be retracted in response to operation of the turn counter, whereby the plunger is operated by its spring, a one-revolution clutch for transmitting motion from the motor, devices moved by said plunger for disaligning the toggle links so that the arbor clutch is disengaged by the first force applying means, and for rendering the one-revolution clutch active, and means driven by the one-revolution clutch for retracting the latch plate from engagement with the lever, for restoring the plunger to normal position in which it is retained by the plunger latch, for restoring the latch plate to normal position wherein it may be reengaged by the lever, and for realigning the toggle links.

38. A coil winding machine having an arbor for winding a coil of wire thereon, a motor, a clutch for connecting the motor with the arbor, a clutch operating member, a spring biasing the operating member into clutch disengaging position, a force transmitting mechanism connected with the clutch operating member, a second spring stronger than the first spring and acting through the force transmitting means to bias the clutch operating member into clutch engaging position, and means automatically responsive to the completion of winding of a layer of wire for rendering the force transmitting mechanism temporarily ineffective whereby the second spring is ineffective to hold the clutch in engaged condition.

39. A coil winding machine having an arbor for winding a coil of wire thereon, a motor, a clutch for connecting the motor with the arbor, a clutch operating member, a spring biasing the operating member into clutch disengaging position, a force transmitting mechanism connected with the clutch operating member, a second spring stronger than the first spring and acting through the force transmitting means to bias the clutch operating member into clutch engaging position, manually operable means for rendering the second spring effective or ineffective, and means automatically responsive to the completion of winding of a layer of wire for rendering the force transmitting mechanism temporarily ineffective whereby the second spring is ineffective to hold the clutch in engaged condition.

40. A coil winding machine having an arbor for winding a coil of wire thereon, a motor, a clutch for connecting the motor with the arbor, a clutch operating member, a spring biasing the operating member into clutch disengaging position, a force transmitting mechanism connected with the clutch operating member, a second spring stronger than the first spring and acting through the force transmitting means to bias the clutch operating member into clutch engaging position, means automatically responsive to the completion of winding of a layer of wire for rendering the force transmitting mechanism temporarily ineffective whereby the second spring is effective to hold the clutch in engaged condition, manually operable means for stressing the second spring so that it overbalances the first spring, means for retaining the manually operable means in spring-stressing position, and means for rendering the retaining means inoperative.

41. A coil winding machine having an arbor for winding a coil of wire thereon, a motor, a clutch for connecting the motor with the arbor, a clutch operating member, a spring biasing the operating member into clutch disengaging position, a force transmitting mechanism connected with the clutch operating member, a second spring

stronger than the first spring and acting through the force transmitting means to bias the clutch operating member into clutch engaging position, means automatically responsive to the completion of winding of a layer of wire for rendering the force transmitting mechanism temporarily ineffective whereby the second spring is effective to hold the clutch in engaged condition, manually operable means for stressing the second spring so that it overbalances the first spring, means for retaining the manually operable means in spring-stressing position, and means for rendering the retaining means inoperative in response to breakage of a wire leading to the arbor from a supply reel.

42. A coil winding machine having an arbor for winding a coil of wire thereon, a motor, a clutch for connecting the motor with the arbor, a clutch operating member, a spring biasing the operating member into clutch disengaging position, a force transmitting mechanism connected with the clutch operating member, a second spring stronger than the first spring and acting through the force transmitting means to bias the clutch operating member into clutch engaging position, means automatically responsive to the completion of winding of a layer of wire for rendering the force transmitting mechanism temporarily ineffective whereby the second spring is effective to hold the clutch in engaged condition, manually operable means for stressing the second spring so that it overbalances the first spring, means for retaining the manually operable means in spring-stressing position, and means for rendering the retaining means inoperative in response to completion of winding of a predetermined number of layers of wire turns on the arbor.

43. A coil winding machine having an arbor for winding a coil of wire thereon, a motor, a clutch for connecting the motor with the arbor, a clutch operating member, a spring biasing the operating member into clutch disengaging position, a force transmitting mechanism connected with the clutch operating member, a second spring stronger than the first spring and acting through the force transmitting means to bias the clutch operating member into clutch engaging position, means automatically responsive to the completion of winding of a layer of wire for rendering the force transmitting mechanism temporarily ineffective whereby the second spring is effective to hold the clutch in engaged condition, manually operable means for stressing the second spring so that it overbalances the first spring, means for retaining the manually operable means in spring-stressing position, and means for rendering the retaining means inoperative in response to breakage of a wire leading to the arbor from a supply reel and in response to completion of winding of a predetermined number of layers of wire turns on the arbor.

44. A coil winding machine having an arbor for winding a coil of wire thereon, a motor, a clutch for connecting the motor with the arbor, a clutch operating member, a spring biasing the operating member into clutch disengaging position, a force transmitting mechanism connected with the clutch operating member, a second spring stronger than the first spring and acting through the force transmitting means to bias the clutch operating member into clutch engaging position, means automatically responsive to the completion of winding of a layer of wire for rendering the force transmitting mechanism temporarily ineffective whereby the second spring is effective to hold

the clutch in engaged condition, a manually operated lever for stressing the second spring so that it overbalances the first spring, a device for retaining the lever in spring stressing position, electro-magnetic means for rendering the retaining device inoperative, and a switch for controlling the electromagnetic means.

45. A coil winding machine having an arbor for winding a coil of wire thereon, a motor, a clutch for connecting the motor with the arbor, a clutch operating member, a spring biasing the operating member into clutch disengaging position, a force transmitting mechanism connected with the clutch operating member, a second spring stronger than the first spring and acting through the force transmitting means to bias the clutch operating member into clutch engaging position, means automatically responsive to the completion of winding of a wire layer for rendering the force transmitting mechanism temporarily ineffective whereby the second spring is effective to hold the clutch in engaged condition, a manually operated lever for stressing the second spring so that it overbalances the first spring, a device for retaining the lever in spring stressing position, electro-magnetic means for rendering the retaining device inoperative, and a switch for controlling the electromagnetic means, said switch being closed in response to breakage of a wire leading to the arbor from a supply reel.

46. A coil winding machine having an arbor for winding a coil of wire thereon, a motor, a clutch for connecting the motor with the arbor, a clutch operating member, a spring biasing the operating member into clutch disengaging position, a force transmitting mechanism connected with the clutch operating member, a second spring stronger than the first spring and acting through the force transmitting means to bias the clutch operating member into clutch engaging position, means automatically responsive to the completion of winding of a wire layer for rendering the force transmitting mechanism temporarily ineffective whereby the second spring is effective to hold the clutch in engaged condition, a manually operated lever for stressing the second spring so that it overbalances the first spring, a device for retaining the lever in spring stressing position, electro-magnetic means for rendering the retaining device inoperative, and a switch for controlling the electromagnetic means, said switch being closed in response to the winding of a predetermined number of layers of wire turns on the arbor.

47. A coil winding machine having an arbor for winding a coil of wire thereon, a motor, a clutch for connecting the motor with the arbor, a clutch operating member, a spring biasing the operating member into clutch disengaging position, a force transmitting mechanism connected with the clutch operating member, a second spring stronger than the first spring and acting through the force transmitting means to bias the clutch operating member into clutch engaging position, means automatically responsive to the completion of winding of a layer of wire for rendering the force transmitting mechanism temporarily ineffective whereby the second spring is ineffective to hold the clutch in engaged condition and a mechanism set into motion concurrently with functioning of the means which renders the force transmitting mechanism temporarily ineffective for effecting the restoration of the force transmitting mechanism to active status after the lapse of a certain period following the disabling of the force transmitting mechanism.

48. A coil winding machine having an arbor for winding a coil of wire thereon, a motor, a clutch for connecting the motor with the arbor, a clutch operating member, a spring biasing the operating member into clutch disengaging position, a pair of normally aligned toggle links connected with the clutch operating member, a second spring stronger than the first spring and acting through the toggle links, when aligned, to bias the clutch operating member into clutch engaging position, but ineffective when the toggle-links are disaligned, means responsive to completion of winding a layer of wire turns on the arbor for disaligning the toggle links, and a mechanism set into motion concurrently with the disaligning of the toggle links for effecting the realignment of the toggle links after the lapse of a certain period following the disaligning of the toggle links.

49. A coil winding machine having an arbor for winding a coil of wire thereon, a motor, a clutch for connecting the motor with the arbor, a clutch operating shaft, an arm pinned to said shaft, a spring biasing said arm into clutch disengaging position, a second arm mounted coaxially with said shaft, toggle links connecting the arms, a second spring stronger than the first and operable through said toggle links, when aligned, to overbalance the first spring and effect the engagement of the clutch, and means for disaligning the toggle links.

50. A coil winding machine having an arbor for winding a coil of wire thereon, a motor, a clutch for connecting the motor with the arbor, a clutch operating shaft, an arm pinned to said shaft, a spring biasing said arm into clutch disengaging position, a second arm mounted coaxially with said shaft, toggle links connecting the arms, a second spring stronger than the first and operable through said toggle links, when aligned, to overbalance the first spring and effect the engagement of the clutch, means responsive to completion of winding a layer of wire turns on the arbor for disaligning the toggle links, and a mechanism set into motion concurrently with the disaligning of the toggle links for effecting the realignment of the toggle links after the lapse of a certain period following the disaligning of the toggle links.

51. A coil winding machine having an arbor for winding a coil of wire thereon, a motor, a clutch for connecting the motor with the arbor, a clutch operating shaft, an arm pinned to said shaft, a spring biasing said arm into clutch disengaging position, a second arm mounted coaxially with said shaft, toggle links connecting the arms, a second spring stronger than the first and operable through said toggle links, when aligned, to overbalance the first spring and effect engagement of the clutch, means responsive to completion of winding a layer of wire turns on the arbor for disaligning the toggle links, and a mechanism set into motion concurrently with the disaligning of the toggle links and acting through the second mentioned arm to move it into position to effect realignment of the toggle links, and to release said second mentioned arm after the lapse of a certain period following the disalignment of the toggle links, whereby the second mentioned spring then operates to reengage the clutch.

52. A coil winding machine having an arbor for winding a coil of wire thereon, a motor, a clutch for connecting the motor with the arbor, a clutch operating shaft, an arm pinned to said shaft, a spring biasing said arm into clutch disengaging position, a second arm mounted co-

axially with said shaft, toggle links connecting the arms, a second spring stronger than the first and operable through said toggle links, when aligned, to overbalance the first spring and effect the engagement of the clutch, a one-revolution clutch for transmitting motion from the motor, means responsive to completion of winding a layer of wire turns on the arbor for disaligning the toggle links and for effecting engagement of the one-revolution clutch, and a mechanism driven by the one-revolution clutch for operating through the second mentioned arm to move it into position to effect realignment of the toggle links, and to release said second mentioned arm after the lapse of a certain period following the disalignment of the toggle links, whereby the second mentioned spring then operates to reengage the clutch.

53. A coil winding machine having an arbor for winding a coil of wire thereon, a motor, a clutch for connecting the motor with the arbor, means responsive to the completion of winding of a predetermined number of turns of wire for effecting disengagement of the clutch, and a motor operated control mechanism set into motion concurrently with the disengagement of the clutch for reengaging the clutch after the lapse of a certain interval following disengagement.

54. A coil winding machine having an arbor for winding a coil of wire thereon in layers, a motor, a clutch for connecting the motor with the arbor, a control mechanism, means responsive to the completion of winding a layer of wire on the arbor for effecting disengagement of the clutch and for causing the control mechanism to be connected with the motor, means operated by the control mechanism for reengaging the clutch after the lapse of a certain interval following disengagement and means for disconnecting the control mechanism from the motor after one cycle of operation of the control mechanism.

55. A coil winding machine having an arbor for winding a coil of wire thereon in layers, means for guiding the wire to the arbor and including feed screws rotating with the arbor, and a lever carrying nut segments engageable respectively with the feed screws, a motor, a clutch for connecting the motor with the arbor, a control mechanism, means responsive to the completion of winding a layer of wire on the arbor for effecting disengagement of the clutch and for causing the control mechanism to be driven by the motor, means operated by the control mechanism for shifting the nut-segment-lever from one feed screw to the other, means operated by the control mechanism for reengaging the clutch and means for disconnecting the control mechanism from the motor after one cycle of operation of the control mechanism.

56. A coil winding machine having an arbor for winding a coil of wire thereon in layers, means for guiding the wire to the arbor and including feed screws rotating with the arbor, and a lever carrying nut-segments engageable, respectively, with the feed screws, means for applying a wrapping of paper to the arbor, a motor, a clutch for connecting the motor with the arbor, a control mechanism, means responsive to the completion of winding a layer of wire on the arbor for effecting disengagement of the clutch and for causing the control mechanism to be driven by the motor, means operated by the control mechanism for shifting the nut-segment-lever from one feed screw to another, means operated by the control mechanism for effecting operation of the paper

applying means, means operated by the control mechanism for reengaging the clutch and means for disconnecting the control mechanism from the motor after one cycle of operation of the control mechanism.

57. A coil winding machine having an arbor for winding a coil of wire thereon in layers, means for guiding the wire to the arbor and including feed screws rotating with the arbor and a lever carrying nut-segments engageable, respectively, with the feed screws, a motor, a clutch for connecting the motor with the arbor and feed screws, a control mechanism, a one-revolution clutch for connecting the control mechanism with the motor, a second one-revolution clutch, a mechanism operated by the motor through the second one-revolution clutch for causing a wrapping of paper to be applied to the arbor, devices responsive to the completion of winding a layer of wire turns for causing the arbor clutch to be disengaged and the first one-revolution clutch to be engaged, means operated by the control mechanism for rendering the second one-revolution clutch operative, means operated by the control mechanism for effecting reengagement of the arbor clutch after operation of the paper applying means, and means for shifting the nut-segment lever from one feed screw to the other.

58. A coil winding machine having an arbor for winding a coil of wire thereon in layers, means for guiding the wire to the arbor and including feed screws rotating with the arbor and a lever carrying nut-segments engageable, respectively, with the feed screws, a motor, a clutch for connecting the motor with the arbor and feed screws, a control mechanism, a one-revolution clutch for connecting the control mechanism with the motor, a second one-revolution clutch, a mechanism operated by the motor through the second one-revolution clutch for shifting the nut-segment lever from one feed screw to the other, devices responsive to the completion of winding a layer of wire turns for causing the arbor clutch to be disengaged and the first one-revolution clutch to be engaged, means operated by the control mechanism for rendering the second one-revolution clutch operative, means operated by the control mechanism for effecting reengagement of the arbor clutch after operation of the nut segment lever shifting means and means for applying a wrapping of paper to the arbor between layers of wire turns.

59. A coil winding machine having an arbor for winding a coil of wire thereon in layers, means for guiding the wire to the arbor and including feed screws rotating with the arbor and a lever carrying nut-segments engageable, respectively, with the feed screws, a motor, a clutch for connecting the motor with the arbor and feed screws, a control mechanism, a one-revolution clutch for connecting the control mechanism with the motor, a second one-revolution clutch, a mechanism operated by the motor through the second one-revolution clutch for causing a wrapping of paper to be applied to the arbor, a mechanism operated by the motor through the second one-revolution clutch for shifting the nut-segment lever from one feed screw to the other, devices responsive to the completion of winding a layer of wire turns for causing the arbor clutch to be disengaged and the first one-revolution clutch to be engaged, means operated by the control mechanism for rendering the second one-revolution clutch operative, means operated by the control mechanism

for effecting reengagement of the arbor clutch after operation of the paper applying means, and after operation of the nut-segment-lever shifting means.

60. A coil winding machine having an arbor for winding a coil of wire thereon in layers, reversible wire guiding means for directing the wire to the arbor in even layers, means for reversing the wire guiding means, means for applying a wrapping of paper to the arbor, a motor, a clutch for connecting the motor with the arbor and with the wire guiding means, a one-revolution clutch, mechanism set into operation in response to the engagement of the one-revolution clutch for effecting the operation by the motor of the wire-guide-reversing means and of the paper applying means, means responsive to the winding of a predetermined number of turns of wire upon the arbor for effecting disengagement of the arbor clutch and for effecting engagement of the one-revolution clutch, and means operated by the motor through the one-revolution clutch for effecting reengagement of the arbor clutch after the wire-guide-reversing means and the paper-applying means have operated.

61. A coil winding machine comprising an arbor upon which a coil of wire is wound in layers, a motor, a high speed primary drive including a clutch connecting the motor with the arbor for winding wire thereon, a low speed secondary drive connected with the motor, a one revolution clutch, means operated by the secondary drive through the one-revolution clutch for applying a wrapping of paper to the arbor and comprising a device for feeding a paper sheet from a supply roll to the arbor, a drive independent of the primary drive for rotating the arbor to wind paper thereon, and means for shearing the paper sheet near the arbor, and a control mechanism rendered active in response to winding of a layer of a certain number of wire turns and operating to disengage the arbor clutch, to effect engagement of the one revolution clutch, and then to effect reengagement of the arbor clutch after the application of paper to the arbor.

62. A coil winding machine according to claim 61 in which the device for feeding a paper sheet to the arbor comprises cooperating feed rolls, one of which is driven through a clutch, and in which a mechanism operated by the one-revolution clutch controls the feed-roll clutch to close it in order that paper may be fed to the arbor and to open it while the arbor is rotated to wind paper thereon.

63. A coil winding machine according to claim 61 in which the drive independent of the primary drive for rotating the arbor includes a clutch, and in which a mechanism operated by the one-revolution clutch controls the last mentioned arbor clutch to close it following the engagement of the one-revolution clutch and to open it before the disengagement of the one-revolution clutch.

64. A coil winding machine according to claim 61 in which the drive independent of the primary drive for rotating the arbor includes a clutch, and in which a mechanism operated by the one-revolution clutch controls the last mentioned arbor clutch to close it following the engagement of the one-revolution clutch to open it during operation of the paper shearing means to close it following the operation of the paper shearing means, and finally to open it before the disengagement of the one-revolution clutch.

65. A coil winding machine according to claim 61 in which the device for feeding a paper sheet

to the arbor comprises cooperating feed rolls, one of which is driven through a clutch, and in which a mechanism operated by the one-revolution clutch controls the feed-roll clutch to close it in order that paper may be fed to the arbor and to open it while the arbor is rotated to wind paper thereon in which the drive independent of the primary drive for rotating the arbor includes a clutch, and in which a mechanism operated by the one-revolution clutch controls the last mentioned arbor clutch to close it following the engagement of the one-revolution clutch and to open it before the disengagement of the one-revolution clutch.

66. A coil winding machine according to claim 61 in which the device for feeding a paper sheet to the arbor comprises cooperating feed rolls, one of which is driven through a clutch, and in which a mechanism operated by the one-revolution clutch controls the feed-roll clutch to close it in order that paper may be fed to the arbor and to open it while the arbor is rotated to wind paper thereon, in which the drive independent of the primary drive for rotating the arbor includes a clutch, and in which a mechanism operated by the one-revolution clutch controls the last mentioned arbor clutch to close it following the engagement of the one-revolution clutch, to open it during operation of the paper shearing means, to close it following the operation of the paper shearing means, and finally to open it before the disengagement of the one-revolution clutch.

67. In a coil winding machine, the combination of a rotatable arbor upon which layers of wire turns separated by paper wrappings are wound, means for winding wire in layers thereon, a mechanism for applying paper to the arbor comprising a drive shaft, cooperating rolls for feeding a sheet of paper from a supply roll to the arbor, a clutch for connecting the drive shaft with one of the feed rolls, a clutch for connecting the drive shaft with the arbor, means operated by the drive shaft for controlling the feed roll clutch so that it closes to cause the paper sheet to be fed to the arbor, means operated by the drive shaft for controlling the arbor clutch so that it closes to cause a certain number of turns of paper to be wound upon the arbor, means operated by the drive shaft for shearing the paper sheet, and means for causing the drive shaft to operate for one cycle of operation of the paper applying mechanism and then to stop.

68. In a coil winding machine, the combination of a rotatable arbor upon which layers of wire turns separated by paper wrappings are wound, means for winding wire in layers thereon, a mechanism for applying paper to the arbor comprising a drive shaft, cooperating rolls for feeding a sheet of paper from a supply roll to the arbor, gears journaled, respectively, on the arbor and on a shaft driving one of the feed rolls, clutches respectively for connecting the gears with the arbor and feed roll shaft, springs respectively urging said clutches into engaged status, a gear driven by the drive shaft and driving aforesaid gears, a cam device operated by said drive shaft for retaining the feed roll clutch in open position except when feeding of paper to the arbor is required, a cam device operated by said drive shaft for retaining the arbor clutch in open position except when winding of paper is required, means operated by the drive shaft for shearing the paper, and means for causing the drive shaft to rotate one revolution and then to stop.

69. A coil winding machine comprising an arbor upon which are wound layers of coil turns alternating with wrappings of paper, a device for guiding wire in even layers upon the arbor, reversible mechanism operating with the arbor for moving the wire guiding device, means for feeding a paper sheet from a supply roll to the arbor, means for rotating the arbor to wind the paper thereon, means for shearing the paper sheet, means for reversing the mechanism for operating the wire guiding device, a shaft for driving all of the aforesaid means, a power shaft, a one-revolution clutch for connecting said shafts and means for controlling the clutch.

70. A coil winding machine comprising an arbor upon which are wound layers of coil turns alternating with wrappings of paper, a device for guiding wire in even layers upon the arbor, reversible mechanism operating with the arbor for moving the wire guiding device, means for applying a wrapping of paper to the arbor, means for reversing the mechanism for operating the wire guiding device, a shaft for driving all of the aforesaid means, a power shaft, a one-revolution clutch for connecting said shafts and means for controlling the clutch.

71. A coil winding machine comprising an arbor upon which are wound layers of coil turns alternating with wrappings of paper, means for rotating the arbor, means for guiding the wire for winding in layers upon the arbor, means for applying a wrapping of paper to the arbor, a shaft connectible with a paper supply roll, a brake cooperating with said shaft for resisting rotation of the supply roll as paper is withdrawn therefrom, and means for varying the frictional resistance afforded by said brake, automatically in response to operation of the paper applying means, the resistance being decreased while the paper is being fed to the arbor and the resistance being increased after the winding of the paper begins.

72. A coil winding machine comprising an arbor upon which are wound layers of coil turns alternating with wrappings of paper, means for rotating the arbor, means for guiding the wire for winding in layers upon the arbor, means for applying a wrapping of paper to the arbor, a shaft connectible with a paper supply roll, a brake cooperating with said shaft for resisting rotation of the supply roll as paper is withdrawn therefrom, means for varying the frictional resistance afforded by said brake, automatically in response to operation of the paper applying means, the resistance being decreased while the paper is being fed to the arbor and the resistance being increased after the winding of the paper begins and manually operable means for controlling the brake resistance independent of the automatic means.

73. A coil winding machine comprising an arbor upon which are wound layers of coil turns alternating with wrappings of paper, means for rotating the arbor, means for guiding the wire for winding in layers upon the arbor, means for applying a wrapping of paper to the arbor, a shaft connectible with a paper supply roll, a brake cooperating with said shaft for resisting rotation of the supply roll as paper is withdrawn therefrom, means for varying the frictional resistance afforded by said brake, and means for operating the paper applying means and for so controlling the means for varying the brake resistance as to cause the brake resistance to decrease below normal while feeding paper to the

75

arbor and then to restore the brake resistance to normal amount after beginning to wind paper, and manually operable means for so controlling the means for varying the brake resistance as to cause the brake resistance to increase above normal.

74. A coil winding machine comprising an arbor upon which are wound layers of wire turns alternating with layers of paper wrapping, means for rotating the arbor, means for guiding the wire for winding in layers upon the arbor means for applying to the arbor a wrapping of a sheet of paper withdrawn from a supply roll mounted upon a shaft, a paper tensioning device comprising a brake shaft connectible with the supply roll shaft, a brake drum connected with said brake shaft, a brake band cooperating with said drum, a spring for urging the band against the drum, a variably positioned abutment member for engaging the spring to vary the force of the spring, a normally stationary member, interconnected toggle links respectively connected with the abutment member and the stationary member, and means responsive to operation of the paper applying means for rotating the toggle links to change the position of the abutment member relative to the normally stationary member.

75. A coil winding machine comprising an arbor upon which are wound layers of wire turns alternating with layers of paper wrapping, means for rotating the arbor, means for guiding the wire for winding in layers upon the arbor means for applying to the arbor a wrapping of a sheet of paper withdrawn from a supply roll mounted upon a shaft, a paper tensioning device comprising a brake shaft connectible with the supply roll shaft, a brake drum connected with said brake shaft, a brake band cooperating with said drum, a spring for urging the band against the drum, an abutment member engaged by the spring and means for adjusting the position of the abutment member automatically in response to operation of the paper applying means.

76. A coil winding machine comprising an arbor upon which are wound a plurality of coils each having layers of coil turns alternating with paper wrappings common to the coils, means for applying wrappings of paper to the arbor, means for cutting the paper wrappings between the end turns of adjacent coils, means for guiding wire in even layers upon the arbor, and a mechanism responsive to movement of the wire guiding means for causing the paper-wrapping-cutting-means to operate.

77. A coil winding machine comprising an arbor upon which are wound a plurality of coils each having layers of coil turns alternating with paper wrappings common to the coils, means for applying wrappings of paper to the arbor, means for guiding wire in even layers upon the arbor, a motor, a primary drive for connecting the motor with the arbor and wire guide, a secondary drive, means for cutting the paper wrappings between the end turns of adjacent coils, a one-revolution clutch for connecting the secondary drive with the paper cutting means, and means for rendering the one-revolution clutch active.

78. A coil winding machine comprising an arbor upon which are wound a plurality of coils each having layers of coil turns alternating with paper wrappings common to the coils, means for applying wrappings of paper to the arbor, means for guiding wire in even layers upon the arbor, a motor, a primary drive for connecting the motor

70 with the arbor and wire guide, a secondary drive, means for cutting the paper wrappings between the end turns of adjacent coils, a one-revolution clutch for connecting the secondary drive with the paper cutting means, and means responsive to movement of the wire guiding means for rendering the one-revolution clutch active.

79. A coil winding machine comprising an arbor upon which are wound a plurality of coils each having layers of coil turns alternating with paper wrappings common to the coils, means for applying wrappings of paper to the arbor, means for cutting the paper wrappings between the end turns of adjacent coils, means for guiding wire in even layers upon the arbor, a mechanism responsive to movement of the wire guiding means for causing the paper-wrapping-cutting-means to operate and pedal operated means for operating the paper-wrapping-cutting means.

80. A coil winding machine comprising an arbor upon which are wound a plurality of coils each comprising layers of wire turns alternating with wrappings of paper common to the coils, means for rotating the arbor, means for guiding the wire for winding in layers upon the arbor, means for applying paper wrappings to the arbor, a plurality of cutter blades mounted for movement from a position removed from the arbor to a position to cut the paper wrappings between end turns of adjacent coils, means for moving the cutter blades, means for variably limiting the extent of movement of the blades toward the arbor, and a mechanism operated by the cutter-blade-moving-means for so operating the movement-limiting-means as to decrease the movement of the blades as the coil diameter increases.

81. A coil winding machine comprising an arbor upon which are wound a plurality of coils each comprising layers of wire turns alternating with wrappings of paper common to the coils, means for rotating the arbor, means for guiding the wire for winding in layers upon the arbor, means for applying paper wrappings to the arbor, a plurality of cutter blades mounted for movement from a position removed from the arbor to a position to cut the paper wrappings between end turns of adjacent coils, means for moving the cutter blades, a rotatable stop plate of variable radius for limiting the extent of movement of the blades toward the arbor and a mechanism operated by the cutter-blade-moving-means for so operating the rotatable stop plate as to decrease the movement of the blades as the coil diameter increases.

82. A coil winding machine comprising an arbor upon which are wound a plurality of coils each comprising layers of wire turns alternating with wrappings of paper common to the coils, means for rotating the arbor, means for guiding the wire for winding in layers upon the arbor, means for applying paper wrappings to the arbor, a plurality of cutter blades mounted for movement from a position removed from the arbor to a position to cut the paper wrappings between end turns of adjacent coils, means for moving the cutter blades, a rotatable stop plate of variable radius for limiting the extent of movement of the blades toward the arbor, a spring tending to return the stop plate to initial position, a ratchet mechanism operated by the cutter-blade-moving-means for rotating the stop plate, a latch for retaining the stop plate in its various positions away from the initial position, and means for retracting the latch to permit said spring to restore the stop plate to initial position.

83. A coil winding machine comprising an arbor upon which are wound a plurality of coils each comprising layers of wire turns alternating with wrappings of paper common to the coils, means for rotating the arbor, means for guiding the wire for winding in layers upon the arbor, means for applying paper wrappings to the arbor, means for tensioning the paper as it is wound upon the arbor, a plurality of cutter blades mounted for movement from a position removed from the arbor to a position to cut the paper wrappings between end turns of adjacent coils, means for moving the cutter blades, means for variably limiting the extent of movement of the blades toward the arbor, a mechanism operated by the cutter-blade-moving means for so operating the movement limiting-means as to decrease the movement of the blades as the coil diameter increases and means for adjusting the paper tensioning means and for causing the return of the blade-movement-limiting-means to initial position to take place.

84. A coil winding machine comprising an arbor upon which are wound a plurality of coils each comprising layers of wire turns alternating with wrappings of paper common to the coils, means for rotating the arbor, means for guiding the wire for winding in layers upon the arbor, means for applying paper wrappings to the arbor, a plurality of cutter blades mounted for movement from a position removed from the arbor to a position to cut the paper wrappings between end turns of adjacent coils, means for moving the cutter blades, means for variably limiting the extent of movement of the blades toward the arbor, a spring resisting movement of the blade-movement-limiting means away from the initial position, a mechanism operated by the blade-moving-means for so moving the blade-movement-limiting-means away from initial position as to decrease the movement of the blade as the coil diameter increases, means for retaining the blade-movement-limiting-means in its various positions away from initial position, and means for retracting the retaining means to permit the spring to return the blade-movement-limiting-means to initial position.

85. A coil winding machine comprising an arbor upon which are wound a plurality of coils each comprising layers of wire turns alternating with wrappings of paper common to the coils, means for rotating the arbor, means for guiding the wire for winding in layers upon the arbor, means for applying paper wrappings to the arbor, means for tensioning the paper as it is wound upon the arbor, a plurality of cutter blades mounted for movement from a position removed from the arbor to a position to cut the paper wrappings between end turns of adjacent coils, means for moving the cutter blades, means for variably limiting the extent of the movement of the blades toward the arbor, a spring resisting movement of the blade-movement-limiting means away from initial position, a mechanism operated by the blade-moving-means for so moving the blade-movement-limiting-means away from initial position as to decrease the movement of the blades as the coil diameter increases, means for retaining the blade-movement-limiting-means in its various positions away from initial position, and means for adjusting the paper tensioning means and for retracting the retaining means to permit the spring to return the blade-movement-limiting-means to initial position.

86. A coil winding machine comprising an arbor upon which are found layers of coil turns alternating with wrappings of paper, a motor, a primary drive for connecting the motor with the arbor, means for guiding the wire for winding in layers upon the arbor, a mechanism for applying wrappings of paper to the arbor and including rolls for feeding paper to the arbor from a supply roll of paper, means for rotating the arbor to wind the paper thereon and means for shearing the paper after a predetermined number of turns of paper have been wound on the arbor, manually operable means for operating said mechanism, and manually operable means operating through a portion of the primary drive for rotating the arbor whereby to vary the number of turns of paper wound upon the arbor before the shearing means operates.

87. A coil winding machine comprising an arbor upon which are found layers of coil turns alternating with wrappings of paper, a motor, a primary drive for connecting the motor with the arbor, means for guiding the wire for winding in layers upon the arbor, a mechanism for applying wrappings of paper to the arbor and including rolls for feeding paper to the arbor from a supply roll of paper, means for rotating the arbor to wind the paper thereon and means for shearing the paper after a predetermined number of turns of paper have been wound on the arbor, manually operable means for operating said mechanism, a secondary drive for connecting said mechanism with the motor, and means controlled by the operator for preventing operation of said mechanism by the secondary drive.

88. A coil winding machine comprising an arbor upon which are wound a plurality of coils each comprising layers of coil turns alternating with wrappings of paper, a motor, a primary drive for connecting the motor with the arbor, means for guiding the wire for winding in layers upon the arbor, a mechanism for applying wrappings of paper to the arbor and including rolls for feeding paper to the arbor from a supply roll of paper, means for rotating the arbor to wind the paper thereon and means for shearing the paper after a predetermined number of turns of paper have been wound on the arbor, manually operable means for operating said mechanism, a secondary drive for connecting said mechanism with the motor, means operated by the secondary drive for cutting the paper wrappings between end turns of adjacent coils, and means controlled by the operator for preventing operation by the secondary drive of the paper applying mechanism and of the paper-wrapping-cutting-means.

89. A coil winding machine according to claim 88 in which the secondary drive operates the paper-applying-mechanism and the paper-wrapping-cutting mechanism through clutches, and the engagement of said clutches is prevented by means controlled by the operator.

90. A coil winding machine comprising an arbor upon which are wound layers of wire turns alternating with layers of paper wrapping, means for rotating the arbor, means for guiding the wire for winding in layers upon the arbor, means for applying to the arbor a wrapping of a sheet of paper withdrawn from a supply roll mounted upon a shaft, a paper tensioning device comprising a brake shaft connectible with the supply roll shaft, a brake drum connected with said brake shaft, a brake band cooperating with said drum, a spring for urging the band against the drum, a variably positioned abutment member

for engaging the spring to vary the force of the spring, a normally stationary member, interconnected toggle links respectively connected with the abutment member and the stationary member, means responsive to operation of the paper applying means for rotating the toggle links to change the position of the abutment member rel-

ative to the normally stationary member and manually operable means for bodily moving the normally stationary member, the toggle links and the abutment member to vary the force of the spring.

JAMES S. BURGE.
